ELECTRICAL MUSICAL INSTRUMENT

Laurens Hammond, Chicago, Ill.

Application April 2, 1938, Serial No. 199,613

49 Claims. (Cl. 84—1)

My invention relates generally to electrical musical instruments and more particularly to instruments of this type in which the tones are produced by translating electrically originated and controlled current pulsations into sound.

The main object of my invention is to produce an electrical musical instrument playable from a keyboard on which it is possible to produce many novel and interesting effects, and at the same time make it possible for a pianist adequately to interpret the great classical works of piano literature.

A further object of my invention is to produce an instrument upon which piano literature can be played, of a tone quality very reminiscent of piano, but with desirable characteristics not heretofore found in the tones of pianos, but which are found only in stringed instruments such as the violin. For example, in the instrument of my invention there may be added to the piano tone a frequency shifting system resulting in a characteristic of the tone resembling the vibrato of a violin.

I am of course aware that electrical pianos have been built in which the hammer action and string have been retained, and by means of electrical translation devices the characteristic motions of the piano string have been translated into sound, through the operation of electrical pick-ups, amplifiers, and speakers. By this process it is possible to build electrical instruments on which standard piano music may be adequately played, but in such systems it is not possible, for instance, periodically to shift the frequency of the various notes. In the instrument of my invention, I do not employ hammers or strings, but seek by purely electrical means to produce the same general acoustical effect as that of the string under various intensities of hammer blow, with the collateral advantage of introducing other novel effects which are hereinafter described.

In order fully to understand the operation of the instrument of my invention, it is necessary to review, in a general way, some of the more obscure acoustic properties of the piano, so as to show what effects are necessary in the electrical system, in order that the music produced will be sufficiently similar to that of the standard piano adequately to interpret the effects intended by the composers of classical piano works.

In the first place, piano notes are, on the average, very complex. That is to say, a very large part of the energy of a single note, especially in the lower register, is contained in the energy of the harmonic frequencies as compared to that

of the fundamental. If all the notes of a concert type of grand piano, which is herein referred to as standard, are played with a blow of the same intensity, which I shall call medium intensity, it will be found that the "brightness" of the notes increases strikingly in playing down the scale. By "brightness" is meant the amount of the total energy contained in the harmonics as compared to the energy in the fundamental. For example, the tones in a piano which I have measured, and the characteristics of which are graphed in Figure 12, the highest A or note No. 85—the notes being numbered consecutively from 1 to 88, the lowest note A, being note No. 1)—has a total energy which exceeds the energy of the fundamental of that note by only 10%. That is to say, about 90% of the energy is that of the fundamental tone, whereas the harmonic energy is only approximately 10%. In going down the scale to note No. 37, which is A below middle C, it is found that the total energy on the harmonics has risen to a value as great as that of the fundamental alone. Harmonic energy then increases steadily and rapidly until for the lowest note of the piano, A, note No. 1, the total energy has risen to a value which is six and one half times as great as the energy of the fundamental frequency alone. So accustomed are we to this tonal arrangement in the piano that we naturally think of these tone qualities as being somewhat the same throughout the range of the instrument, whereas, by physical measurement they are entirely unlike in harmonic development.

If, instead of playing each note with the same intensity of blow, a single note is selected and played with intensities of blows ranging from the softest to the hardest, it will be found that the sound produced changes in two major respects. In the first place, it will be found that the total energy increases enormously with the hard blow, the relationship being such that the total energy is approximately in direct proportion to the energy imparted to the key. The energy in an electric circuit is proportional to the square of the current or voltage. The energy necessary to move the key is proportional to the square of the velocity imparted to the key, so it follows that in general, to simulate the touch response of a standard piano in an electrical instrument, it is necessary to produce an output signal of which the voltage is directly proportional to the velocity with which the key is struck. However, with key blows of increasing intensity on a standard piano, the audibility of the note increases even more rapidly than its total energy increases,

because of the shift in the harmonic energy distribution. This is the second major effect. If a harmonic analysis is made of a soft note and then of a loud one, resulting from a change in the strength of blow delivered to the key, it will be found that the brightness of the note has increased along with an increase in intensity. The increase in brightness means that a larger proportion of energy is carried by the harmonics with the increasing strength of blow, which adds to the audibility, especially in the lower range, where the higher harmonics fall in the region of maximum sensitivity of the ear.

Thus, the skilled pianist has under his control, not only the loudness, but the harmonic content of the note, depending on the way in which he strikes the key. In the electrical instrument herein described, I have provided means whereby the key, which operates switches in timed succession, rather than actuating mechanical mechanisms such as hammers, is nevertheless so arranged as to be touch responsive in the same way as is the piano key. I mean by that, that the acoustic energy output will very closely approximate the square of the velocity with which the key is struck, and that the brightness of the note will increase with increasing key blow intensity, but in a manner which can be regulated in the electrical instrument, whereas it cannot be so regulated in the piano, except by taking out the hammers and changing the dimensions and properties of the felt covering the hammers, or changing the shape of the relatively harder cores of the hammers themselves.

Whereas, as stated above, the acoustic energy output of the piano is approximately proportional to the energy of the key blow, this relationship does not hold true for very light blows. In the standard piano there is a threshold value of key velocity below which there is no energy output. This is due to the fact that the velocity with which the key is struck must be sufficient to throw the hammer far enough to reach the string. This limits the pianist in very soft passages because if he attempts to play more and more softly he reaches a point where his technique no longer permits him to play each note with equal intensity, or at least with the intensity which he desires and expects. This is one of the features of the standard piano which I believe can be improved upon, and it is therefore a further object of the invention to make the key operate in such manner that there is no threshold of key velocity below which the acoustic energy falls to zero. The operation of the key has been made such that the lowest possible velocity produces a threshold value of acoustic output. It therefore follows that there is a small range of intensities of key blows, all of them exceedingly soft, which gives rise to the same energy output and therefore greatly facilitates the pianist's technique in soft passages.

A further important characteristic of the standard piano is the way in which the sound decays after the key is struck and held down. Once the string is set in motion, its energy is gradually transferred to the sounding board and the acoustic output decreases in a logarithmic fashion to approach the value of zero asymptotically. That is, it would theoretically require an infinite length of time for the string to come to rest. The rate of decay of the sound is strikingly different for the highest notes and the lowest ones—the lower notes sounding much longer. The exact rate of decay plays a very im-

portant part in determining the characteristics of the piano tone. In the instrument of my invention, the rate of decay may be controlled, and the constants of the circuit are so arranged as to give, with at least one particular setting, the same rate of decay as that of the standard piano. If these values are departed from, the instrument may produce most interesting and novel effects, but the similarity to the piano will immediately be lost and many works of piano literature cannot adequately be played if these constants be appreciably changed.

We have seen therefore that a piano note consists of a complex tone quality which starts suddenly and thereafter decays logarithmically to zero. This is not the whole story. This may be illustrated by the use of an electric organ of the type disclosed in my U. S. Letters Patent No. 1,956,350 granted April 24, 1934. On this instrument it is possible to set up a tone quality which for any particular note in the middle range may be quite similar to that of the standard piano. By pressing the key and closing the swell pedal while so doing, it is possible to make the note come on instantly and decay logarithmically to a lower level. In this case, however, the quality of the note does not change as it decays. While the note sounds generally like a piano note, there is a certain definite difference noticeable to the ear. To simulate the piano, it is necessary that the electrical apparatus be such that each note have a different harmonic content depending on the intensity with which it is sounding. This is similar to the effect discussed previously in connection with soft and hard key blows. Owing to the fact that the note, when loud, is brighter than when it is soft, the audibility of the note as it decays, decreases more rapidly at the start than the straight logarithmic decay of a note of constant harmonic content. As far as I am aware, I am the first to propose an instrument without hammer or strings in which this characteristic of the sound of a string struck by a hammer is obtained, and it is therefore a further object of the invention to reproduce this effect.

A further characteristic of the standard piano lies in the fact that the tone of a piano note, especially in the lower register, is made up of a fundamental and a long series of partials, which partials are not true harmonics of the fundamental—in the sense that they are of frequencies which are not exact integral multiples of the fundamental. This is due to the fact that whereas the string continues to generate sound over a considerable period of time, it is not continuously excited, but receives all of its energy during the blow of the hammer. If the string were an ideal one—that is to say, having no stiffness of its own, a uniformly distributed mass in a diameter which could be completely neglected by comparison with its length—then it could be shown that such a string would give rise to partials of frequencies which were exact harmonics of the fundamental. This is not the case in the standard piano as may quickly be shown by watching the pattern shown on a cathode ray oscilloscope operated from a microphone picking up the sound of a piano note. If all the partials of the tone were exact harmonics, the shape of the pattern would not change appreciably during the decay of the note. Actual experiment will immediately show small amplitude high frequency waves which travel rapidly along the wave produced by the lower frequencies.

Pianos are usually tuned by a beat system, and

whereas the methods of tuning differ in detail, all of them tend to expand the musical scale in such a way that the highest notes of the scale are sharp and the lower notes are flat.

Let us assume therefore, that a piano has just been tuned in accordance with the best practice, and assume further, that double octaves are struck, for instance, A's Nos. 13, 25, 37 and 49. The second harmonic of the lowest A(13) is very close in frequency to the fundamental of the A(25) an octave higher. Similarly, the fourth harmonic of the A(13) is of a frequency in the vicinity of the fundamental of the A(37) two octaves higher, and in the vicinity of the second harmonic of the A(25) one octave higher. The eighth harmonic of the lowest A(13) is close in frequency to the fundamental of the A(49) three octaves up and close to the fourth harmonic of the A(25) one octave higher, and close to the second harmonic of the A(37) two octaves higher, etc. Now it is not possible to tune these four A's so that there will be no beats between them. Not only is it not possible to do so in a practical sense, but it is theoretically impossible as well. Without therefore considering the effects of the tempered musical scale which introduces beats in chords where notes of other than unison pitches are involved, it will be seen that beats will occur between frequencies which are close to one another and which are derived from the different notes of chords.

Further, beats are introduced for another reason. Except for the very lowest notes of the standard piano, either two or three strings are used for each note. The multiple strings cannot be tuned exactly alike as a practical matter, or even if they were, they would not remain so for very long after tuning. Chords played on a freshly tuned piano give rise to groups of frequencies which are very close to one another but are not the same. The amounts of their differences are not of an order to suggest to the listener that the piano is out of tune, but these frequency differences play a very important part in characterizing the general effect and in giving "life" to the tone. This is due to the fact that when two frequencies which are close to one another are temporarily in phase with one another they reinforce each other, whereas when they are temporarily out of phase they tend to cancel one another. Thus, the acoustic spectrum is continuously changing—certain frequencies coming on while others are going off, etc. These effects are generally similar to the effect of a vibrato on a stringed instrument such as a violin.

In listening to the piano, one is ordinarily not aware of the vibrato effect because of the fact that a vibrato is associated in our minds with a definite simple rhythmical change such as is heard when a violinist rocks his finger on the string. In that case, he changes the effective length of the string in such a way as periodically to raise and lower the pitch. This is a change in frequency which, together with the pattern of the enclosure in which he is playing, produces at the listener's ears a change both in frequency and in intensity.

A simple vibrato on a melody instrument such as the violin occurs at a periodicity which may be counted by a listener. Depending on room conditions and other factors, this may sound very much like a tremulant to the listener, and there is no very clear difference, under some circumstances, between a vibrato, which is customarily thought of as a periodic change in frequency, and

a tremulant, which is usually defined as a periodic change in intensity. The effect of the vibrato is enhanced by applying it at different frequencies to different notes, such that when a chord is played no definite rhythmic beating is perceptible. It may be stated in a general way, that when the listener becomes conscious of such rhythm to the extent that he is aware of the beat itself rather than of the effect of warmth which it gives to the tone, the effect is then unsatisfactory to many listeners. He is never able to count the vibrato effects of the piano and has therefore come to think of the piano as an instrument without vibrato, which is not the fact in a technical sense. Very strong vibrato effects are present in the standard piano, but they are of a very complex nature. The beats between the different frequencies do not last long because the notes decay, and there are a great many different rates of beat going on at the same time. To count them it is necessary to focus the attention on one particular beat and to start to count. Time does not permit much in this process, because before the rate is established clearly in the mind, the effect is gone.

In the instrument of my invention, I have a system for continuously shifting the frequencies of each note in a rhythmical manner. Thus, if a single note is played, the effect may be counted, if the attention is attracted to it, as is the case with the solo violin note. I provide a method, however, for putting a different vibrato rate on the different notes so that when chords are played there are many vibratos of different rates going on at the same time. This produces an effect too complex for the listener to analyze mentally—in the sense that he is unable to pick up these complex rhythms before they are gone. The shifting of the frequencies of different notes in a manner in which one is independent of another produces a musical effect which is highly desirable. The complex tone of a chord, as in the standard piano, is then made up of many groups of frequencies which are shifting in audibility, so that some are growing more prominent while others are becoming less so. The specific means for accomplishing this result is not shown herein but is disclosed in detail and claimed in my co-pending application Serial No. 199,612, filed April 2, 1938.

Other and more specific objects of my invention will be apparent from the following description, reference being had to the accompanying drawings in which:

Figures 1 and 2 together constitute a wiring diagram of a representative portion of the instrument.

Figures 3 to 9a inclusive show wave forms, illustrating the operation of the distortion and control tube.

Figure 10 is a graph showing the effect of the velocity of depression of the keys of the instrument.

Figure 11 is a wiring diagram showing the adjustable potential supply means for the circuits shown in Figures 1 and 2.

Figure 12 is a graph showing the relative energy in the fundamental and the harmonics of a piano tone.

Figure 13 is a transverse sectional view of the keyboard and associated switches.

Figures 14 to 18 inclusive are sectional views of the keyboard taken on the lines 14—14, 15—15, 16—16, 17—17 and 18—18 respectively, of Figure 13.

Figure 19 is a chart showing the harmonic development of a number of notes.

Figure 19a is a wiring diagram showing the setup used to obtain the readings charted in Figure 19.

Figure 20 is a chart showing the effect of increased key velocity upon the harmonic development of the note.

Figure 20a is a diagram showing the setup utilized in obtaining the readings charted in Figure 20.

Figures 21 to 27 inclusive are various intensity envelope diagrams showing a number of different ways in which the intensity of the note sounded may be varied.

Figure 28 is a diagrammatic representation of a modified form of note control switch mechanism.

Figure 29 is a diagrammatic front elevational view of the unitary bus contact bar; and

Figure 30 is a view similar to Fig. 29 showing a sectionalized bus contact bar.

General plan of instrument

I believe that a better understanding of the invention will be obtained if the general operation of the instrument as a whole is first outlined. As a complete instrument it includes thousands of parts, including at least 180 vacuum tubes with their circuits, power supply systems, amplifiers, etc. The whole instrument may be divided into five general systems as follows: (1) Generator system; (2) Control tube system; (3) Touch responsive keyboard; (4) Touch control system; and, (5) Output system.

Generator system

The generator system includes 88 alternating current generators which are continuously operating to produce frequencies of a tempered musical scale corresponding to the 88 notes of the standard piano. The generator system per se forms no part of the invention hereinafter described, being the subject of my aforesaid pending application, Serial No. 199,612, filed April 2, 1938.

While any one of a number of suitable high audio-frequency generators known in the art could be used, but for a number of considerations which will appear later, I prefer to employ 88 oscillating vacuum tubes. In one of the arrangements which I prefer, there are 12 vacuum tube oscillators which I refer to as master oscillators, and which oscillate at the frequencies of the 12 highest notes of the piano. In addition to this, there are 76 tubes, only one of which is illustrated in Figure 1 as tube 280. These tubes are special 3 element gas filled tubes and they operate as relaxation oscillators. The grid of each such tube receives a signal from a secondary winding 288 of a transformer, the primary of which is in the plate circuit of a similar tube one octave up. Thus, the frequency at which each gas tube "relaxes" is controlled, in cascade fashion, from a frequency twice as great, produced by another similar relaxation oscillator which is supplying the signal for a note one octave higher. By means which it is unnecessary here to describe, the frequency of every gas tube oscillator for similar notes in each octave, such as the A, for instance, is thus derived from the frequency of the master oscillator for the note A of the highest octave of the instrument. If this last frequency be shifted up and down through a small range, or even several notes, the pitch of every other A

for the entire instrument will shift accordingly. The generator system also includes (but not shown in this application) a selectively operable system for periodically shifting the frequencies of all the master oscillators, at different rates, so that the control tubes 284 hereinafter described do not necessarily function at steady frequencies.

Control tube system

The control tube system includes 88 vacuum tubes, one for each note, for which purpose I prefer to use pentodes with sharp cutoff characteristics. Only one of these tubes is illustrated as tube 284 in Figure 1, and its operation is described in detail elsewhere. Briefly, this tube is continuously receiving a signal from the corresponding relaxation oscillator for that note, this signal being applied to the control grid 282. All of these control tubes are connected to transmit the signal from their plates P-49, P-50, etc., into a common output circuit described hereinafter. They do not normally supply any signal, however, because of the fact that the cathode of each tube is connected to the common ground of the system by means of the condenser C4, and unless the cathode receives direct current through a resistance R7, it is of necessity cut off, and no plate current is available to carry a signal to the output circuit. This means that if any direct current flows through the resistance R7, such current will be immediately "chopped up" into impulses which pass into the output system, as a result of the continuously varying potential of the grid 282. The amplitude of these impulses will depend wholly on the amount of direct current supplied to the cathode from the touch responsive keyboard.

Touch responsive keyboard

The keyboard includes 88 keys of conventional piano dimensions. When struck, they move down to stop against a felt cushion, and when released, they are brought to rest in their upward motion by a mechanical damper. Under each key are several electrical switches which operate in succession, the making and breaking of different contacts occurring in regular succession in accordance with the motion of the key, so that the electrical events occurring in the circuits associated with these switches take place in succession with a rapidity which is wholly determined by the velocity of the key on its downward stroke. One of the switches shown as switch 282, 286 of Figure 1, is adapted to be operated upon by a spring catch 274 which is controlled by a foot pedal 270 corresponding to the damper or sustaining pedal of the standard piano. The general purpose of the switches, operated by the keys and sustaining pedal, together with their associated circuits, is to supply to the control tube system impulses of direct current which are to be converted into signals by the operation of the control tubes 284 just described.

Thus, the direct current supplied from the keyboard switches to the control tubes 284 may be thought of as determining the envelopes of the waves transmitted by the control tubes to the output system. Thus, if the direct current supplied by the keyboard system be one which starts suddenly, continues at the same rate for a period of time and then suddenly stops, the signal transmitted from the control tube to the output system will resemble a sustained note, such as an organ note, for example. If, on the other hand, the direct current supplied by the keyboard sys-

tem starts suddenly and then immediately begins decreasing in a logarithmic fashion, the note produced will resemble that of a percussion instrument, such as a piano. Thus, the switches 5 operated by the keys merely control direct currents and it would therefore be possible, if it were desired, to place the keyboard system at a distance from the rest of the apparatus, in the same manner that organ consoles may be placed 10 remotely from the body of the instrument. Except for a common ground return, only one wire per note would be necessary for this purpose.

Touch control system

15 Unlike any other musical instrument with which I am familiar, the instrument of my invention contains means whereby the player may instantly control the touch responsive behavior of the keyboard upon which he is playing. This 20 touch control system includes a number of separate controls described in detail elsewhere, whereby the velocities of key motion may produce different effects not only in the control of the envelope of intensity, but also in the quality of 25 each note. This is accomplished in a general way by shifting the direct current potential of different points in circuits associated with the key and sustaining pedal operated switches.

Output system

30 This system includes circuits whereby the output of all the control tubes can be combined, modified, controlled as to intensity, amplified, and transmitted to an electrical output system 35 for conversion into sound waves in a manner generally similar to that employed in electric organs, but with such modifications as are described in detail hereinafter.

Key action and switches

40 The keyboard employed in the instrument of my invention will, in external appearances, resemble that of the standard piano and extends throughout the tonal range customary in standard 45 pianos, namely, throughout 88 notes commencing with A⁻¹ and extending to C⁷. For convenience, the notes of the piano are herein designated by their respective numbers, 1 to 88.

While the key action per se does not form a 50 part of the subject matter claimed herein, a brief description thereof is believed to be necessary for an understanding of the invention as a whole, and I have therefore illustrated in Figures 13 to 18 inclusive, 29 and 30, the more important 55 parts of the key action, especially as it is related to the subject matter of the invention claimed herein.

For each of the notes there is a key 200, preferably of a molded plastic composition of the 60 general character disclosed and claimed in my co-pending application, Serial No. 91,283 filed July 18, 1936, which has matured into Patent No. 2,117,002, granted May 10, 1938. The keys 200 are suitably secured to key bars 202 which 65 are pivoted upon a rod 204, the latter being suitably secured in a keyboard assembly and being supported adjacent each group of keys by the upwardly projecting portions 206 of key frame plates 208. There is riveted to each of the key 70 bars 202, adjacent its rearward end, an off-set downwardly extending arm 210, to the lower end of which one end of a tension spring 212 is secured. The other end of the tension spring 212 is anchored to bar 214 extending lengthwise of 75 the keyboard and provided with adjusting screws

216 by means of which the bar 214 may be moved forwardly or rearwardly in guide slots 217 formed in frame plates 208 to vary the tension of the springs 212 and thus adjust the keyboard as a whole, or any portion thereof, for any desired key tension or "touch".

Upward movement of the key is limited by a thin flexible metallic strip 218, the lower end of which is suitably anchored by means of clamping strips 220, and the upper end of which is secured to the forward end of the key bar 202. Upon depression of the key, the strip 218 bows forwardly as indicated by the dotted lines in Figure 13.

Suitable means is provided to prevent rebound 15 of the key as it returns to its uppermost position. This means comprises a snubber consisting of a fabric ribbon 222, one end of which is clamped to the center of the strip 218, and the other end of which is shown as secured to the upper free 20 end of a leaf spring 224. In actual practice the latter may be secured to a suitable adjustable clamping means 225 whereby its effective length may be adjusted to maintain a slight initial bow in the strip 218. The ribbon 222 passes partially 25 around snubber rods 226, 228. As the key is depressed to its lowermost position, and the strip 218 bows forwardly to its dotted line position, the spring 224 will take up the slack produced in the ribbon 222 so that upon the return stroke of 30 the key, the ribbon will be under tension applied by the spring 224, and due to its frictional contact with the snubber rods 226, 228 will dissipate energy at a rate increasing as the key approaches the upper limit of its stroke and as the strip 218 35 resumes its normal position as shown in full lines in Figure 13. As a result, the key will return to its normal position without any rebound whatsoever despite the fact that the tension of the spring 212 is sufficiently great relative to the 40 rotary moment of inertia of the key bar and parts carried thereby, that the return stroke of the key is very rapid.

Downward movement of the key is limited by a felt pad 230, which is suitably mounted upon a cross-bar 232 extending longitudinally of the keyboard, which has notches 233 receiving portions of the frame plates 208, being held in engagement with the latter by screws 234. Suitable means for guiding the forward ends of the key bars 202, and for holding the plates 208 in properly spaced relation, are provided, but it is believed to be unnecessary to describe these parts in detail in this application.

Each of the keys is provided with a suitable 55 bearing bracket 236 which is secured to the key bar 202 and at its lower end is provided with a pivoted touch-response switch arm 238. This arm pivots freely but is forced to move clockwise (Fig. 13) by a tension spring 240, one end 60 of which is suitably anchored to a terminal part 241 fixed to the key bar 202 (but insulated therefrom), and the other end of which is secured to the tall portion 242 of the switch arm 238. When the key is in its normal upper position, the 65 switch arm 238 makes contact with a bus contact 244, which may extend the full length of the keyboard as shown in Fig. 29 or may, if desired, be made in separate sections such as the sections 244a, 244b, and 244c shown in Fig. 30, each section for one or more keys. Adjacent the bus contact 244 is a contact 246 individual to each key, while forwardly of the latter there is an insulating strip 248, and forwardly of the insulating strip is a third contact 250 individual to each 70 75

key. The upper edges of the contacts 244, 246, 250 and insulating strip 248, are at different elevations, so that upon depression of the key 200, the contact arm 238 will successively make contact with the contact 246; break contact with the contact 244; break contact with the contact 246; and make contact with the contact 250. Upon the return stroke of the key, these contacts are made and broken by the contact arm 238 in the reverse order.

The "repeat" switch comprises a pivoted arm 252 carried by a bracket 254 secured to the key bar 202. The repeat arm 252 does not pivot freely, but a certain amount of friction is provided so that the arm will not be moved by the forces of gravity and momentum to which it may be subjected. The arm 252 projects through an aperture 256 formed in an insulating strip 258, and is adapted shortly prior to the completion 15 of the downward stroke of the key to make contact with a contact 260, the contact with this contact 260 being broken just prior to the completion of the down stroke of the key and just prior to the time rocker switch arm 238 makes 20 contact with contact 260. Upon the return stroke 25 of the key the switch arm 252 does not make contact with the bus 260.

A sustaining switch arm 262 is suitably clamped at 264 and is in the form of a leaf spring having a contact making element 265 at its rear free end which is adapted to close a circuit by contacting with a contact member 266. In normal position, as shown in Figure 13, the circuit is completed between the switch contact arm 262 and contact member 266. Upon depression of the key, an actuator 268 which is carried by the key bar 202, is adapted to engage the contact arm 262 and move the rearward free end of the latter away from the contact 266, thereby opening the circuit.

40 the circuit.

45 A shaft 269 is pivotally mounted in the frame plates 208 (other suitable bearings may be provided) and may extend the full length of the keyboard, or may be made in two or more sections. The shaft 269 is adapted to be moved clockwise (Fig. 13) by means of a sustaining pedal 270 (illustrated schematically in Fig. 1), the sustaining pedal being connected by a suitable tension member 271 with an arm 272 secured to the shaft 269. If the shaft is made in two or more sections, each section may be provided with a separate sustaining pedal and linkage for actuating that section of the shaft, duplicating the parts 269, 270, 271 and 272 shown in Fig. 1. For example, the instrument may be provided with a shaft section 269 which extends throughout the treble register of the keyboard and a similar shaft section for the remaining keys of the keyboard, each section being controlled by a separate sustaining pedal. The sustaining pedals, however, are preferably so positioned that the player may easily with one foot selectively depress either of the sustaining pedals, or both of them.

The shaft, or shaft sections, 269 have secured thereto resilient latches 274 which, when the shaft 269 is swung clockwise by the depression of the sustaining pedal, will press against the ends of the sustaining switch arms 262. If the latter are in their uppermost position, the pressure of the resilient latches 274 against the ends thereof will not have any effect. If, however, a key is being held down while the sustaining pedal is depressed, the resilient latch 274 associated therewith will swing above the free end 75 of the sustaining switch arm 262 and hold the

latter away from its complementary contact 266, when later the key is released, as long as the sustaining pedal is held depressed. Similarly, if keys are operated while the sustaining pedal is being held depressed, the sustaining switch arms 262 of such keys will be engaged by their respective resilient latches 274, and these switch arms 262 will thereby be held away from their associated contacts 266 until the sustaining pedal is released and the resilient latches 274 thus 10 swung counterclockwise (Fig. 13) out of the path of movement of the free ends of the sustaining switch arms 262, whereupon these arms will resume their normal positions in contact with contacts 266.

From the above description it will be seen that the depression of a key will result in switching operations in the following sequence:

- (a) Making contact between switch arm 238 and contact 246; 20

(b) Breaking contact between switch arm 238 and bus contact 244;

(c) Breaking contact between switch arm 238 and contact 246.

(d) Making contact between repeat switch arm 252 and contact 260; 25

(e) Breaking contact between switch arm 252 and contact 260;

(f) Breaking contact between sustaining switch arm 262 and its complementary contact 266; 30

(g) Making contact between switch arm 238 and contact 250; and upon the return stroke:

(h) Breaking contact between switch arm 238 and contact 250; 35

(i) Closing contact between sustaining switch arm 262 and its complementary contact 266 (if the sustaining pedal is not depressed at the time the key is released);

(j) Making contact between switch arm 238 and contact 246; 40

(k) Making contact between switch arm 238 and bus contact 244;

(l) Breaking contact between switch arm 238 and contact 246.

and contact 260. 45
The functions and effects obtained by the sequence of switching operations above set forth, will be apparent from the description of the circuits and their operation which appears herein-after. The key action and associated switches, as distinguished from the combinations in which these elements are used, are disclosed in greater detail and are claimed in my copending application Serial No. 216,336, filed June 28, 1938. 50

Oscillator generators

As previously stated, the oscillators for the various note frequencies may be of any of the well-known types, but I prefer to use vacuum tube oscillators for the twelve highest frequencies and may use gas filled tube relaxation oscillators for the remaining 76 notes. The gas filled tube oscillators have their frequencies controlled by means of the master oscillators, each master oscillator controlling the frequency of the gas tube oscillators which are of the same note in the octave, i. e., whose frequencies bear a sub-multiple octave relationship to the frequency generated by the master oscillator. The gas tube oscillators of a series are controlled in cascade in a manner such that the master oscillator controls the frequency of the gas tube oscillator which has a frequency one-half that of the master oscillator, and this gas tube oscillator controls the frequency of the next gas tube oscillator.

lator of the series which has a frequency one-fourth of that of the master oscillator, and one-half the frequency of the preceding gas tube oscillator, etc. This system or method of generating oscillations of the frequencies of the tones of the musical scale is disclosed in greater detail, and is claimed in my copending application Serial No. 199,612, filed April 2, 1938. Another simpler and less costly arrangement is to have the oscillations of the master oscillators successively divided by two by means of the frequency divider circuit disclosed and claimed in my co-pending application Serial No. 199,614, filed April 2, 1938.

In Fig. 1, I have illustrated one such gas filled tube relaxation oscillator as comprising a gas filled triode 280. The plate circuit of each oscillator includes a resistance 282 and an inductance 284 (which constitutes the primary of a transformer, the secondary of which is connected in the grid circuit of the gas tube oscillator generating a frequency which is an octave lower than that of the oscillator illustrated), a source of adjustable direct current potential 286, a resistance R_{17} and a resistance R_{18} . A condenser C_{15} is connected between the source 286 and the cathode of the tube 280. The grid of the tube 280 is connected to ground through a resistance 287 and an inductance 288, the latter constituting the secondary of the transformer by which the stabilizing signal from the oscillator of a frequency twice that of the oscillator illustrated is impressed upon the grid of the tube 280. The resistance R_{17} is shunted by a condenser C_{14} and may be shunted by an additional condenser C_{16} upon closure of a switch 290. The signal from this relaxation oscillator is taken from the point P between the resistances R_{16} and R_{17} and is impressed upon the control grid 292 of the control tube 294. The heaters for the cathodes of tubes 280 and 294 are omitted from Fig. 1 for the sake of clarity. A description of the operation of this oscillator will appear hereinafter.

Control tube and circuits

The functions of the control tube are four-fold: (a) It serves as a distorting tube to change the harmonic content of the note fed to the output circuit from that of the signal which is applied to its grid; (b) it serves to control the envelope of the energy output, beginning at cutoff, when the note is not sounding, to maximum intensity, and progressively to lower intensities, and finally to cutoff again; (c) it serves as a means for changing the harmonic content of the note in a manner which results in increasing the brightness with increasing output intensity; (d) lastly, the tube operates in such a way that it makes possible a wide variety of tone qualities supplied to the output circuit by a change in the value of a condenser connecting its control grid to ground. A change in the value of this condenser changes the sharpness of the positive peak of the signal impressed on the grid, and this change produces a change in the harmonic content of the output signal in a manner which is entirely different from the effect a condenser would have in a linear circuit.

The cathode of the control tube 294, of which there is one for each note of the instrument, is connected to a terminal N which is connected to the ground through a blocking condenser C_1 . A high resistance R_7 is connected between a junction M and the terminal N. The junction M is connected to ground through a blocking con-

denser C_7 . The junction M may be connected to a direct current source of adjustable potential through a resistance R_{14} upon closure of a switch 296 which is connected to terminal G. The junction M is connected to a terminal D through a resistance R_6 , the terminal D being connected to a direct current source of adjustable potential.

The junction M is connected through a resistance R_8 with a terminal L, which latter is connected to the fixed repeat switch contact 260. The repeat switch arm 252 is connected by a conductor 298 with a terminal F, which in turn is connected to a direct current source of adjustable potential. A resistance R_{10} is connected between terminal L and a terminal K, which is the terminal on the sustaining switch contact 266. The resilient sustaining switch arm 262 is connected to a terminal E, which in turn is connected to a direct current source of adjustable potential. A resistance R_9 is connected between the junction M and the terminal J on the contact 250.

The contact 246 is connected through a resistance R_{13} to terminal B, which in turn is connected to a direct current source of adjustable potential. The bus contact 244 is connected to a terminal A, which is connected to a direct current source of adjustable potential. The touch response switch arm 238 is connected to a terminal H, the latter being connected through a resistance R_{12} to a terminal 300, and the latter terminal is connected to ground through a condenser C_8 , and connected to terminal C through a high resistance R_{11} , the terminal C being connected to a direct current source of adjustable potential.

The screen grid 302 of the control tube 294 is connected to a source of direct current of adjustable potential, while the suppressor grid 304 may be grounded. The plate $P-49$ of the tube 294 is preferably connected to a wire 306 in parallel with the plates $P-50$, $P-51$ and $P-52$ which are the plates of the control tubes 294 for the adjacent notes Nos. 50, 51 and 52.

Operation of control tube and circuits

I will first describe the operation of the tube 294 with respect to its control of the energy output. When playing the instrument as a piano this energy output is of course changing all the time from the beginning of the note when it rises suddenly, until the end, when the tube is again cut off by release of the key or release of the sustaining pedal, in the event the latter has been used. The tube I prefer is a pentode having sharp grid cutoff characteristics. A tube of the type 6C6, for instance, is satisfactory. The control grid 292 receives a continuous signal from a generator, which in this case is illustrated as a continuously oscillating vacuum tube. One of the systems which I prefer, and which is herein partly shown and described, is the three-electrode gas filled tube 280 previously mentioned, but which might be some other form of oscillator or generator.

The screen 302 of the control tube 294, like the screen of the control tube for every other note, is supplied with a steady potential of 25 volts. The suppressor 304 is connected to ground and the plate is continuously supplied with voltage, (at point 312, Fig. 2) in this case some 200 volts, from an output circuit which receives the signal from all the control tubes. Since the cathode is connected by means of the condenser C_4 to

ground, and by means of the high resistance R_7 to the touch responsive key circuit, no direct current can flow to the cathode of the control tube unless it does so by way of the high resistance R_7 . Thus, if the control tube 294 is not supplied with direct current from the key circuit, it cannot continue to function to transmit the signal (which is continuously put on its grid 292) to the output circuit. When direct current stops flowing in R_7 the potential of the cathode will shift in the positive direction such that the control grid becomes more negative with respect thereto, until the tube is cut off. In this condition there is no output signal despite the fact that the grid continues to receive an input signal, and the plate P-49 is shielded from the capacitative effect of the grid by the screen 302 and suppressor 304. The key circuit, which is described elsewhere herein, controls the direct current component of the pulsating current in the cathode circuit. The impedance of the tube 294 from cathode to ground for direct current is extremely small by comparison with the impedance of the resistance R_7 . This is due to the fact that if the potential of the point N with respect to ground should change by a very small amount in the negative direction, an enormous plate current would immediately flow through the tube.

The control tube may be thought of as normally cut off. As soon as cathode current is supplied from the key circuit, the direct current potential of the cathode will shift slightly such that the next most positive excursion of grid potential will be just sufficient to allow an impulse of current to pass through the tube during a fraction of the cycle of grid voltage. During the remainder of the cycle the tube will be cut off, and the potential of the cathode will again be sinking in the negative direction for another impulse of current on the succeeding positive grid swing.

To understand the operation, it may be convenient to think of the tube as a device whereby whatever direct current is supplied by the resistance R_7 to the cathode, will be immediately "chopped off" by the tube and delivered in impulses to the output circuit, the frequency of these impulses being of course determined by the frequency of the signal which is continuously supplied to its grid. If the current supplied by the resistance R_7 be double, for instance, then the cathode current will be doubled and so will the average value of plate current. The control tube operates to amplify the signal supplied to its grid and to transmit a signal to the output circuit, but it does not act as a linear amplifier. The harmonic content of the output differs from that of the input, and the tube may therefore be thought of as a distortion device. It is the particular type of distortion which is here of interest and which may be explained as follows:

In the circuit illustrated in Figure 1 the signal applied to the grid 292 of the control tube 294 is derived from a generator having an output which is not a sine wave. I may use a sine wave, however, and in the preferred form of construction do use a sine wave for the highest octave of notes. If a sine wave is supplied to the grid, the tube functions for only a portion of the cycle during the period of most positive grid excursion, so that the quality of the output is dependent on the shape of only that portion of the input signal wave which is sufficiently positive to operate the tube.

To illustrate this point, there is shown in Figures 3 to 6 inclusive a number of different input

waves which would result in the same output signal, illustrated in Figure 9a. The harmonic content of these various input signals would be entirely different, and yet the output would be the same because the shapes of the upper parts of the waves above the dot-dash cut-off lines, are similar in each case. The distortion introduced by the tube is therefore of a peculiar nature. A sine wave input will produce an output wave which may be rich in harmonics.

If the output wave, such as that shown in Figure 9a, is connected to a harmonic analyzer (using a circuit such as shown in Figure 19a) and the amount of energy of each harmonic is measured separately, it will be found that the amplitude of each harmonic bears a simple relationship to the amplitude of all other harmonics. This relationship is a simple geometric one in which if the amplitude of the fundamental is unity and the amplitude of the second harmonic is, for example, .8, then the amplitude of the third harmonic will be $.8 \times .8$ or .64, and the amplitude of the fourth harmonic will be $.8 \times .64$ or .512, etc. If the amplitude of each harmonic be plotted on semi-logarithmic paper, a series of points such as that shown in Figure 19 will be obtained, and it will be found that these points lie on a straight line with a high degree of accuracy. If the amplitude of the input wave be changed, a different series of harmonics will be obtained, but in this case the points will again fall in a straight line with a difference in the slope of the line.

The harmonics present from what appears to be an infinite series extending upward in frequency in accordance with this formula as far as the measuring apparatus will permit. In measurements which I have made, the ratio of energy between the 42nd and 43rd harmonics, for example, will be found to be just the same as that between the second and the third harmonic. The complete harmonic analysis of tone is therefore determined by simply specifying the difference in intensity measured in decibels between any harmonic and the next succeeding one. This is of course the same as specifying the slopes of the lines in Figure 19, and I therefore refer to this slope in terms of decibel decrease per harmonic number as, for instance, 2.05 db/H for note No. 25. The curves of Figure 12 are plotted with a value of db/H as abscissas and various energies as ordinates. For a wave having a fundamental of a given amplitude it will be found that the total energy increases very rapidly as the harmonic content increases, corresponding to analyses in which the db/H factor decreases. This factor is therefore a convenient measure of the brightness of the tone.

Except for the highest octave of notes, each of the control tubes 294 obtains its signal from a relaxation oscillator shown as comprising the gas filled triode 280 in Figure 1. In the cathode circuit of this tube are two resistors R_{16} of 300,000 ohms, for example, and the resistance R_{17} of 10,000 ohms. A pulsating direct current flows through these resistors and the wave of this current is of a saw-tooth nature illustrated as the curve shown in Figure 7. The voltage developed across the resistance R_{17} would be of the same shape were it not for the effect of the condenser C_{14} , which shuts it. If this condenser be of proper value, the voltage across the mesh of the resistance R_{17} and the condenser C_{14} will be of wave form illustrated in the curve of Figure 8.

It will be noted that the curve of Figure 7 is

of saw-tooth form, one leg of which is almost vertical, and there is a sharp corner to the wave on the most positive and negative points. The excursion of voltage in the positive direction does not produce a vertical line because of the impedance in the plate circuit of the tube which does not permit of an instantaneous change in charge of the condenser C_{15} . The slope of this portion of the curve may be controlled by changing the constants in the plate circuit. The curve of Figure 8 shows the effect of the condenser C_{14} which has the effect of rounding off the most positive portion of the wave. The shape of the most negative part of the wave is substantially unaffected. Comparison of this curve with the curves of Figures 3, 4, 5 and 6 will show that only the most positive part of the wave is of importance in determining the signal put out by the control tube. Thus, a saw-tooth wave may be employed in the same manner as a sine wave, and the harmonic content of the output of the control tube will have the same general characteristics as those described for the sine wave input.

An additional condenser C_{16} may be shunted across the condenser C_{14} by means of the switch 290. In a complete instrument this switch is a gang switch, operating to ground one end of a similar condenser provided for each note for which a relaxation oscillator is used as the generator. With the added capacity, C_{16} , the curve representing the voltage at the point P (with respect to ground) now changes to a shape more like that of curve of Figure 9. In this wave the positive loop is rounded off even more.

Figure 20 shows the result of the analysis of the harmonic content of the signal put out by the control tube of note No. 25 of a complete instrument. The circuit used and the constants used are shown in the diagram, Figure 20a. Five different series of points were obtained which may be joined by substantially straight lines, representing the voltages of each separate harmonic entering into the composition of the wave. The five different lines arise from five different voltages of the battery B_1 . These curves show how an increase in this voltage produces an increase in the energy of the output signal, and more particularly, how the harmonic content of the resulting note changes with an increase in intensity. The slope of each line is denoted by the "brightness factor" db/H previously described, and it will be noted that the "decibel decrease per harmonic number" changes from a value 2.75 for the softest note to 1.41 for the loudest, and that this change is systematic. Further experiments have shown that the harmonic content of the output may be controlled in two major respects by changing the values of C_{14} and C_4 respectively. For any given battery voltage the slope of the line, or db/H factor may be changed by changing the value of the condenser C_{14} . Once this slope is established for a certain battery voltage, the rate of change of slope with increasing and decreasing battery voltage may be largely controlled by the proper selection of the value of the condenser C_4 . The desirability of the brightness change to simulate piano-like effects was described previously.

In Figure 19 are plotted the harmonic analyses for a plurality of different A's of the complete instrument. The same battery voltage was used in each case, and was of a potential corresponding to the starting potential of a blow considered to be of medium strength. In this case,

the values of the condensers C_{14} and C_4 for each note are arrived at by "voicing" the instrument in such a manner as most closely to approximate the tone quality for a similar blow on a certain concert grand piano of well known make. The curves show the enormous change in the harmonic content for the same note in different octaves. Similar curves plotted for different intensities of blows show the same general arrangement, except, of course, that all notes are more harmonically developed with increasing strength or blow.

Operation of touch responsive key circuits

As previously described the touch responsive key circuit is connected as shown in Figure 1, in which, when the key is in its upper position of rest, the rocker arm 238 electrically connects the point H with the terminal A. As the key goes down, the rocker arm connects H to B through R_{13} and opens the connection between H and A. After a period of time, depending upon the velocity with which the key is moving, the contact from H to B (through resistance R_{13}) is in turn broken and when the key is all the way down, contact is made between H and J.

When the key has been depressed a certain distance the damper switch 262-266 connecting E to K is likewise opened. When the key is allowed to return upward this switch will again be closed unless it is held open by the action of the sustaining pedal 270 which operates to turn the shaft 269 through a small angle in a clockwise direction. In that event, the damper switch will remain open regardless of whether the key is allowed to rise or not.

The repeat arm 252 whose mechanical operation has been described, connects the terminal L with the terminal F for a brief period during only the down stroke of the key. The circuit from L to F is open both at the top and at the bottom of the key stroke and the parts are so dimensioned that contact is made on the down stroke at about the same time that the rocker arm 238 is passing over the insulating strip 248, so that at that time, point H is not connected to either A or J.

The terminals A, B, C, D, E, F, and G are, for purposes of illustration, each connected by means of a battery to ground. The switch 296 is herein assumed to be open. These batteries are merely to indicate that each of these points is to be held at a fixed potential relative to ground. The voltage on each one of these points may be adjusted in accordance with the requirements of the player. In actual practice, such batteries would not be used, but the fixed potentials would be secured from a single source of direct current supply by shunting this supply with a tapped resistor in a manner well known in the design of power supply systems for radio sets and the like and as described hereinafter with respect to Figure 11. By means of various multiple switches, hereinafter described in detail, the performer may change the potential of each one of these points independently in order to obtain a different mode of operation for the circuit.

In order to explain the operation of the key circuits we will assume that the performer wants to obtain a normal touch responsive action which will closely approximate that of the standard piano. In that case, he will make such adjustments that the potential at the various points with respect to ground is as follows: A at minus 450 volts, B, C and F at ground, D and E at plus 6 volts. The points A, B, C, D, E, F, and G are 75

common for all notes of the keyboard, (or, if desired, for only certain registers thereof) but the values of the resistors or condensers, or both, may change from note to note. Assuming that the 5 diagram applies to note No. 25, for instance, then good values for the various elements are as follows: C_7 and C_8 , .3 mfd; R_7 and R_{11} , 4 megohms; R_{12} and R_{13} , 6000 ohms; R_8 for this note may have a value of zero and consequently be omitted, (but 10 for higher notes R_8 may be considerable); R_9 , 10,000 ohms; R_{10} , 600,000 ohms; and R_6 20 megohms.

I prefer to make the condensers C_8 and C_7 of the same capacity, and it will be noted that one 15 end of each is connected to ground. The charges on these condensers vary during the playing of the note, the general plan being that a charge on C_8 is carried and delivered to C_7 . A simple mechanical analogy may be used to illustrate the 20 operation as follows: A runner has a bucket with which he is carrying water from a lake to fill a tank. The bucket has a hole in it. On his way between the lake and the tank, the water is continually running out of the bucket. He always 25 starts with a full bucket but when he reaches the tank, he may have much or little, or no water at all, depending on how fast he ran. If he goes slowly enough he will obviously arrive with no water. In this analogy, the condenser C_8 is the 30 bucket. Condenser C_7 is the tank. The hole in the bucket is the resistance path from B through the resistance R_{13} , the rocker arm to H, the resistance R_{12} to the bucket condenser C_8 . The lake is the source A, the potential of which is 450 35 volts more negative than ground.

With the key up before the down-stroke of the key, the potential across C_8 is that of the source A, and the condenser therefore has a high negative charge. The potential across C_7 is the same 40 as that of the points D and E which were both assumed to be at the same voltage, namely, plus 6, with respect to ground. No current is flowing in the resistance R_7 because the control tube 284 is cut off.

45 Assume that the key is struck very violently. In that case, connection through the rocker arm 238 from H to B will not last long, and despite the fact that B has been assumed to be at ground potential, time will not permit a great discharge 50 of the "bucket" condenser C_8 because of the resistances R_{12} and R_{13} in the circuit. As a result, when the connection H to J is established through the rocker arm 238, the charge on the condenser C_8 will be something less than 450 volts, say for 55 example 250 volts, depending of course on how hard the key was struck. As soon as the rocker arm 238 establishes contact between H and J, the two charges on C_7 and C_8 will begin to equalize. This takes only a very short time because of the 60 low resistance of R_{12} and R_9 , and as a result, the potential at the point M will suddenly shift from its previous value of a low potential with respect to ground to a potential about halfway towards minus 250 volts, or say minus 125 volts.

65 Had the key been pressed very slowly the potential delivered by C_8 would be substantially nothing. That is to say, its charge would be substantially lost and when the connection H to J was established the condensers C_8 and C_7 would 70 neither of them have any substantial charge. In that event, the potential at the junction point M would be left substantially unchanged.

In Figure 10, a curve has been plotted in which the abscissa is the velocity of key motion. The 75 ordinates are the voltages of the point M at the

start of the note. These voltages are not obtained, of course, until after a very short period of time when the two condensers C_8 and C_7 have had their charges equalized through the path from M through R_9 to J to H and through R_{12} . 5

It will be noticed that if the velocity of the key is near zero, the voltage of point M will likewise be close to zero. As the velocity increases to 1, voltage begins to rise slowly, the curve being shown as the curve A-10. 10

The characteristics of the control tube and the constants of the circuit are such that the tube is cut off when the cathode is at a voltage of plus 6 volts with respect to ground. Accordingly, if the cathode is more positive than plus 6 volts, there is 15 no direct current path from the point N through the resistance R_7 to ground. Likewise, the point N always remains at a potential which is exceedingly close to plus 6 volts with respect to ground, because as soon as any current flows through R_7 20 tending to make the point N grow more negative, the current through the tube will increase very sharply. For operation of the key circuit it may therefore be assumed that the point N is always at a fixed potential of plus 6 volts with 25 respect to ground.

It will be seen that when the point M is at a voltage of zero with respect to ground, there is therefore 6 volts difference between the point M and the point N, and there is therefore a small 30 current flowing through the resistor R_7 . This is the cathode current of the tube and there is, therefore, a signal, albeit a small one, with M at the potential of zero.

From the curve in Figure 10, it may therefore 35 be seen that if the velocity of the key is anything less than 1, the intensity of the signal will be substantially constant and may be represented by the voltage between the cutoff voltage of the tube and the voltage of the point M. A straight line 40 F-10 drawn from plus 6 volts and zero velocity toward the point B-10 will therefore represent a theoretical value which the voltage of point M should have if the intensity of the signal, expressed in volts, was exactly proportional to the 45 key velocity. This relationship will be exactly true at three points where the straight line intersects the curve A-10, namely, at C, D and E. The agreement, generally speaking, is very close except for very low velocities, which gives this 50 system a great advantage over the touch responsiveness of the standard piano, for reasons previously described.

The constants of the circuit, especially the values of the resistors R_{13} and R_{12} must be so 55 chosen that the hardest blow which a good pianist can deliver to the key will not carry the voltage of the point M a great deal beyond the point E-10, where the curve A-10 begins to depart more and more rapidly from the straight line. 60 If this precaution is not observed, the instrument might be used to advantage by one who was accustomed to it, but there would be a range of hard blows which would all result in intensities which differed only slightly from one another. 65

Assume that the key has been struck and held down so that there is a connection from H to J, and the point M has reached a negative potential with respect to ground, of 125 volts. There are now three paths whereby the charge on the condensers C_7 and C_8 may leak off. One path is through the resistance R_7 to the point N, the potential of which is plus 6 volts. Another path is through the resistance R_{11} to the point C, the potential of which is zero, and the third is through 70 75

the resistance R_8 to the point D which was assumed to be set at a potential plus 6 volts. The resistance R_6 is of an extremely high value, being preferably about five times as great as either R_7 or 5 R_{11} , which are alike. For the present, we may disregard this path because its effect is small by comparison with the other two. Likewise, when the key is down, there is no discharge path through the resistance R_{10} because the damper 10 switch 262, 266 is open and there is no path between E and K. Owing to these discharge paths, the voltage at the point M starts to decay in the manner characteristic of a charged condenser discharging through a resistance. The voltage, 15 with respect to elapse of time, decreases along a curve which asymptotically approaches zero, or, in this case, approaches a value one-half way between the voltage of C and N. C is at zero voltage and N is at plus 6 volts, so that if the key were 20 held down indefinitely, the potential of the point M would reach the value plus 3 as a constant value. This is upon the assumption that the effect of the circuit through R_8 may be neglected. Under these circumstances, it means that if the 25 key is struck and held down indefinitely, that the note will never completely die away, but will reach a steady value of which the voltage is approximately one-half of that of the signal which the very softest blow would produce.

30 Supposing now that the key was struck with the same velocity as before, and was subsequently released, but the sustaining pedal 270 was operated for the purpose of keeping the note sounding. In that case, the connection from E to K remains 35 open despite the fact that the connection from H to J is broken, and the connection A to H is restored. In this case, the circuit between the two condensers C_8 and C_7 has been broken so that the total capacity which is discharging is cut in half 40 (being only the charge on C_7). However, the rate of decay remains the same as though the key had been held down because the leakage path through the resistance R_{11} has been disconnected along with the disconnection of the capacity C_8 . The 45 total leakage path of R_7 and R_{11} has been cut in half to match the reduction in capacity, so the time constant remains the same. In this event, the voltage across C_7 will eventually decrease to be exactly the same as the voltage across C_4 , and 50 the signal will decay logarithmically to an intensity determined by the potential of the point D.

The repeat arm 252 serves a number of functions. If the potential of the point F with respect 55 to ground is zero, as was here assumed, it will operate in such fashion as to bring the voltage of the junction M to a value close to zero during the down stroke of the key, no matter what the previous history of the operation of the key and 60 sustaining pedal has been just prior to that time. This is of special importance in the case where the key is repeatedly struck with the sustaining pedal held depressed. If the repeat arm were omitted in this case, a number of blows struck 65 in rapid succession would result in "pumping up" the voltage across C_7 in a cumulative manner. The repeat arm 252 and its associated circuit prevents this, as it cancels the effect of the previous down stroke of the key in each instance so that 70 the effect of each blow is the same, regardless of the previous blow.

In the standard piano, the effect of repeated 75 blows on one note with the sustaining pedal on, produces certain undesirable effects not under the control of the pianist. This is because the string

is vibrating from the effect of a previous blow when struck, and it is a matter of chance as to what portion of the cycle of string vibration is taking place at the instant the subsequent blow is struck. Thus, the second blow sometimes tends 5 to augment, and sometimes tends to cancel, the residual effect of the preceding blow, giving an erratic effect well known to skillful pianists. In the instrument of my invention, this erratic effect is removed, and I consider this to be of considerable 10 advantage.

Supposing now that the key is struck and shortly thereafter released without making use of the sustaining pedal. In that event, the connection from E to K is established as soon as the key is 15 released, and the condenser C_7 will discharge rapidly through the resistor R_{10} , so that the voltage of the point M will quickly reach the same voltage as the point E. Thus, the voltage of the point E must be set to such value as will insure 20 safe cutoff for the control tube 294. Of course there will necessarily be some slight differences in the characteristics of different tubes, and 88 such tubes are required for an 88 note instrument. In practice, the voltage of the point E can be set by 25 means of a potentiometer or the like, to that point where every note is cut off when the instrument is not being played. It is not good to have the voltage unnecessarily positive for normal piano-like operation. The value of the resistance 30 R_{10} determines the rate of decay of the note when the key is released. This time should not be too short, so that if the instrument is played in a room which is acoustically too "dead", the notes will 35 continue to ring for about the same length of time as they do when a standard piano is played in a room having a reverberation time best suited for piano playing. By making the resistance R_{10} larger, it is possible to introduce a certain type of 40 artificial reverberation. The best value is a matter of taste.

Touch control system

I have thus far described the operation of a 45 circuit to simulate standard piano performance. By changing the voltages of the points A, B, C, D, E and F, (assuming that switch 296 is open) it is possible to produce other effects too numerous to describe in detail, but a few of the effects may be 50 described as follows:

Supposing, for instance, that the voltage of A and B is made the same, and that a voltage of 55 minus 250 volts is selected. In that event, the note will be the same as it was in the previous case when the key was struck with a certain specified velocity used in the previous example, but in this case, the effect will be totally independent of key velocity. The softest blow and the hardest one will produce identical notes, and yet the tone 60 quality will be just as pianistic as before. The intensity may, of course, be controlled by selecting the voltage to which both A and B are jointly connected.

Another effect is produced by having A and B 65 at voltages which are closer to one another than the standard setting. In this case, the notes are touch responsive to key velocity, but not to the same extent as previously. Suppose, for instance, that A is left at minus 450, but B is changed from 70 zero, or ground potential, to a value such as plus 45. In this event, all blows of low velocity come out the same at an intensity which is considerable. Rapid passages may then be played in which each 75 note is of the same precise intensity as the previ-

ous one, and yet the ability to accentuate certain notes above this common level is not lost.

Supposing that the player now wishes to produce the effect of an organ. In that event, notes must not decay as do piano notes, but must start and continue at the same level regardless of key velocity. This may be accomplished in different ways, one of which is to put D, E and F together at plus 6; A and B and C together at a value such as minus 100 volts. In this event, the charge on the condenser C₈ will be 100 volts at the instant when the connection H to J is established, and this voltage will be divided approximately in half when the charges on C₇ and C₈ have been equalized. This voltage will not decay, however, because current will flow through R₁₁ at the same rate as it does at R₇ and this voltage will continue indefinitely as long as the key is held down. The note is therefore sustained as it is with an organ, but the instrument has an added feature not found in organs. The sustaining pedal may be used, whereupon if the key is released, the note will begin to decay from the level of the organ tone in the same manner that a piano note decays.

A new and very useful type of control may be obtained by piano and organ-like combinations, in which all blows up to a certain velocity produce steady organ tones, which persist as long as the keys are held down, but if a harder blow is struck, the notes will have a pianistic attack under touch responsive control, and then decay to a steady organ intensity. All the various effects possible can be ascertained only by continuous trial and practice, provided that the voltages of the various points A, B, C, D, E, F and G can be individually manipulated by the player. Many of the effects do not, of course, appear to be musically useful. By reversing the potentials of A and B, for instance, it is possible to have the keys operate in such a manner that the harder they are hit, the softer the note, and vice versa. It is probable that such an effect would never be musically useful, but who can say. Likewise, if the potential of C or D is much more negative than the starting potential of M with respect to ground, then the notes will gradually grow in intensity, and many orchestral and unusual effects can be obtained.

The resistance R₈, which may be zero and consequently omitted for the lower notes, plays an important function for higher notes. It limits the rate at which the charge on C₇ can change the beginning of the note. If this resistance be large, the attack of the note will be less sharp and the effect of "key thump" noticeable in the higher notes of the standard piano may be avoided. We are, however, so much accustomed to this "key thump" in the higher notes of the piano that its complete removal is distasteful to many. It may be removed in part, however, and produce an improvement in part, however, and produce an improvement in the estimation of the majority of listeners.

As previously described, there is a change in the harmonic content of the note with change in average plate current of the control tube. It follows therefore, that changes in quality as well as intensity may be made in the manipulation of the voltages for the points A to F. For instance, organ-like notes of different levels will have different harmonic contents. Thus, if the A, B and C voltages are less negative, the quality will be less harmonically developed. A volume control 346 (Fig. 2) in the output circuit can make the overall intensity the same, and a quality difference at the same loudness level can thus be obtained.

In Figure 1 is shown a resistor R₁₄ which may

be connected by means of a switch 298 to the point G, the potential of which may be controlled. The switch 298 is not operated by the key and in a complete instrument comprises a gang switch, so that similar switches, one for each key, may be opened or closed simultaneously. In the description heretofore, it has been assumed that this switch was always open as illustrated in Figure 1. The normal use of this part of the circuit is to make the potential of G the same as that of E and to have both of them at the point where the control tubes are just cut off. In this case, when the switch 298 is closed, the resistance R₁₄ serves as a rapid discharge path for the condensers C₇ and C₈ when the key is down. This rapid decay of the note makes possible effects wherein the instrument is reminiscent of a banjo or a xylophone, in which the notes die away quickly.

Figure 11 illustrates the wiring and switch elements of the touch control system. A source of direct current of about 460 volts is diagrammatically illustrated as a battery 390. The negative terminal is connected through a series of resistors 391 to 397 to ground, the values of these resistors decreasing progressively in resistance as indicated in Figure 11. The positive terminal is connected to ground through a variable resistance 398 of 200 ohms having an adjustable contactor 399.

On a control panel 399a above the keyboard of the instrument are five rotatable pointers which are connected to multi-contact switches 400 to 404, or to a movable arm of a potentiometer. The five multi-contact switches 400 to 404 illustrated, supply the voltage for the points A, B, C, D and F respectively referred to by these letters in Figure 1. The multi-contact switch for the point D of Figure 1, is not strictly necessary and could be omitted if desired. Similarly a multi-contact switch could be supplied for controlling the potential of point G, but this is not essential and is omitted from Figure 11 for the sake of simplicity.

Under each control appears a legend which may guide the player who is not thoroughly familiar with the instrument, so that he may experiment and arrive at different useful results from the touch control system. When he moves the potentiometer 398, 399, he is actually shifting the potential of the point E with respect to ground, thus finding the point at which the instrument becomes silent when he is not playing, that is, when there is no current flow through the resistance R₇. The five multi-contact switches 400-404 may each have numerals from zero to eight representing eight steps of intensity, and like numerals on different switches may refer to the same intensities.

The legends associated with the multi-contact switches 400-404 indicate the character of the adjustment effected by the respective switches. Switch 400 is marked "Max. intensity with hard blow" indicating that the setting of this switch to a higher number will cause the maximum intensity of the note sounded to increase correspondingly when the key is struck with a hard blow.

The multi-contact switch 401 is marked with the legend "Min. intensity with soft blow" indicating that this switch controls the minimum intensity at which a note will sound when the key is struck softly.

Switch 402 bears the legend "Final intensity with key held down" indicating that by shifting this switch to higher numbers, the terminal in-

tensity of the tone may be raised to an increased level.

The switch 403 is marked "Final intensity with key released but damper off" indicating that by shifting this switch to a contact of higher potential, the final intensity of the note may be at a higher value if the sustaining pedal is depressed.

The switch 404 bears the self-explanatory legend "Intensity just prior to bottom of stroke".

The lever 408 controls the switches 296, and the adjacent panel bears the legends "Standard", "Fast" and "Decay of note", indicating that when the lever 408 is set for "fast" decay of the note, the switches 296 will be closed and the notes will die away quickly as in the banjo and xylophone, whereas when the lever 408 is set for "standard" decay, the decay of the notes will be at a rate determined by other factors.

A study of these legends together with the diagram of Figure 1 and the previous description will show the various possibilities of touch control which can be obtained. For example, supposing the player wishes to set up a simple organ arrangement, which is not touch responsive, at a medium intensity such as intensity 4. In that case, he will realize that "minimum intensity with soft blow" should be the same as "maximum intensity with hard blow", and he will accordingly set the A and B switches 400, 401 to the same point, namely, the point marked 4. He will also realize that the "final intensity with key held down" is to be the same as the start of the note, and he will adjust the C switch 402 to the position 4. Similarly, he will want the "intensity just prior to bottom of stroke" to be zero, and he will set that switch accordingly. The potential of D determines the final intensity of the note. In "organ" playing the damper or sustaining pedal may effectively be used to cause the notes to decay gradually after the key has been released.

The lever 408, Figure 11, labelled "Decay of note" and having two positions, "Standard" and "Fast", operates the multiple switches 296 of Figure 1, permitting the player to cut in or out the resistance R_{15} for each note. In a more simple instrument, the point G is permanently connected to the point E, and the resistance R_E and the point D, Figure 1, may be eliminated entirely.

Intensity envelopes of notes

In Figures 21 to 27 inclusive, are illustrated exemplary diagrams showing a variety of note intensity envelopes which may be produced by different settings of the various controls of the instrument. In each instance, the ordinates represent the intensity of the note produced while the abscissas represent the time elapsed after depression of the key.

In Figure 21 the curves show the various kinds of piano-like envelopes which may be produced upon depression of the key. The curve 21—A is the envelope of a note produced when the key is struck a maximum blow, while curve 21—B represents the envelope of the note produced when the key is depressed at minimum velocity. The intermediate curves represent the envelopes of the notes produced upon depression of the key at various intermediate velocities. To obtain these effects, the potential difference between the terminal A (Figure 1) and the terminal E is made high, while the potential difference between terminals B and E is made low. The potential difference between F and E is likewise low, the potential difference between terminals C and E is

relatively low, and the potential difference between terminals D and E is made less than C. It will be noted that the curves 21—A and 21—B as well as the intermediate curves approach the point 21—C logarithmically, this point representing the time at which the key is released. If the sustaining pedal has not been depressed prior to the release of the key, the note will decay logarithmically along the dotted curve 21—E, whereas if the sustaining pedal has been depressed prior to the release of the key, the note will decay logarithmically to the point 21—D, the ordinate of which is determined by the potential of terminal D and the abscissa of which represents the time that the sustaining pedal is released. Upon release of the sustaining pedal, the note will decay rapidly to zero intensity.

The envelope represented by curve 21—B is of interest in that it shows the intensity envelope of a note which is obtained with the lightest possible key blow. This curve illustrates the fact previously mentioned that the instrument of my invention has the advantage, as compared with a standard piano, of sounding the note no matter how lightly the key is depressed, whereas in the standard piano, a certain minimum blow is required to cause the note to sound.

The intensity envelope curves of Figure 22 represent notes produced when the controls are adjusted as previously described with respect to Figure 21 except that terminals C and D are at the same potential and differ from the potential of terminal E to a greater extent than in the setting resulting in the curves in Figure 21. The initial portions of the note envelope curves are determined by the velocity of key depression but after a certain interval, the notes will sound at a given intensity irrespective of the velocity of depression of the key. For example, the curve 22—A represents the envelope of the note produced upon depression of the key with maximum velocity, while the curve 22—B represents the envelope of the note produced upon depression of the key with minimum velocity. The intermediate curves, as before, represent the envelopes of the notes produced upon depression of the key with various intermediate velocities. All of the note envelope curves eventually attain the intensity represented by the point 22—C, the intensity of the latter being determined by the potential of the terminal C. If the key is released at the time represented by the point 22—C, the note will decay rapidly as represented by the dotted line 22—E. If, however, the key is held depressed, or the key released after the sustaining pedal has been depressed, the note will continue to sound at the intensity represented by the point 22—C until the key is released or the sustaining pedal released at the time represented by the point 22—D, whereafter the note will decay rapidly along the line 22—F. The note envelopes represented in Figure 22 are very desirable since they give the effect of a combination piano and organ. When the controls of the instrument are adjusted to produce envelopes of this character, the instrument may be said to be adjusted for touch responsive organ, since the initial portion or attack of the note is responsive to the velocity of key depression while the terminal portion of the note is of predetermined intensity as in an organ.

Figure 23 represents the envelopes of notes produced with the controls set similarly to the settings producing the envelopes of Figure 22,

except that the potential of terminal F is varied to produce the three different curves representing different kinds of attack of the note. The curve 23—A is the envelope of the note produced when the potential difference between terminal F and terminal E is relatively high, while curve 23—B represents the note envelope when the potential of terminal F is near that of terminal E. The slight jog at 23—G is caused by the temporary closure of repeat switch contacts 252, 260 which causes a temporary drop in the potential of the point M with respect to the potential of E.

The curves of Figure 24 represent the envelopes produced when terminals A and B are of the same potential, the different curves representing the envelopes produced by simultaneous change in the potentials of A and B. The intensity represented by the point 24—C which is attained by the note after a predetermined elapse of time is determined by the potential of terminal C, while the rate at which the note decays from the point 24—C to the point 24—D is determined by the potential of the terminal D. As in the previously described envelope diagrams, the dotted line 24—E represents the decay of the note when the key is released without having previously depressed the sustaining pedal. The family of curves of Figure 24 show musically interesting note envelopes in which the shape of the envelope is not affected by the velocity of key depression; i. e., the instrument is not touch responsive, but in which a uniform combination piano and organ effect may be obtained.

The note envelope curves in Figure 25 represent a variety of envelopes which may be obtained by a combination of the above described conditions which are productive of the envelopes shown in Figures 21 and 24. In Figure 25, the family of curves is obtained by maximum velocity of key depression, and there would be a similar family of note envelope curves for each key velocity. This family of curves represents the envelopes of notes produced when the settings of the potentials of terminals A and B are the same as described with reference to Figure 21, but the settings of the potentials of terminals C and D are equal but simultaneously varied.

Figure 26 represents the note envelope which may be produced when it is desired to play the instrument as an organ. To produce these envelopes, the potentials of terminals A and B are set to the same value. The repeat is set sufficiently high and the potentials of C and D are made the same and may be set at the control point marked 3 in Figure 11. This envelope will follow the dotted decay line 26—E if the key is released without having previously depressed the sustaining pedal, while it will otherwise continue at the same intensity to the point 26—D at which time it is assumed that the sustaining pedal is released. Due to the relatively rapid attack and decay of the note, the envelope is substantially identical with that of an organ note.

The family of note envelope curves shown in Figure 27 may be obtained by settings of the controls similar to those used to produce the envelopes of Figure 21, except that the potential of the point C is at cut-off of the control tube. As a result, the note always dies away to zero intensity. The curve 27—A represents the note envelope produced when the key is depressed with maximum velocity, while the curve 27—B represents the envelope when the key is depressed at relatively low velocity, the curve 27—G representing the envelope when the key is depressed at an intermediate velocity.

While the families of curves of Figures 21 to 27 inclusive show a large variety of intensity envelope diagrams of notes which may be produced by the instrument, they are merely examples. From a consideration of the curves which are shown, there will be obtained a general idea of the different effects obtainable by different settings of the various controls and it will be apparent that by further combinations of settings of the controls, a very large number of different note envelopes may be obtained. In addition, intensity of the music being produced may be varied by means of the swell pedal or similar volume control. Ordinarily, when the controls are set so that the instrument is touch responsive, the swell pedal will not be used during the playing of a complete selection. However, when the controls are set for organ-like notes, the swell pedal will usually be used to obtain the intensity changes required in rendering a selection.

Output circuits

Figure 2 shows the important elements of the output circuit of the instrument. In a complete instrument, the control tubes 294 are divided into groups of four tubes of consecutive notes, and have their plates joined together in parallel as indicated in Figure 1 wherein the plates P—49 to P—52 (for notes 49 to 52) are connected in parallel to a wire 306, while the plates P—73 to P—76 for the control tubes of the notes 73 to 76 are connected in parallel to a wire 308, and the plates P—11 to P—14 for the notes 11 to 14 are connected in parallel to a wire 310. The output circuits of the eighty-eight control tubes 294 of the complete instrument are thus brought out by 22 wires, only three of which are illustrated, as the wires 306, 308 and 310. The wires 306 and 308 and their associated networks are representative of wires connecting groups of control tubes for the higher notes of the musical scale, while wire 310 and its associated network is representative of the wires from the control tubes of the lower notes.

A source of potential 311, let us say 250 volts, is connected between terminal 312 and ground, so that the point 312 is fixed at a positive potential with respect to ground. The wire 308 leads to a terminal 314. The terminal 314 may be selectively connected to a terminal 316 (and hence to the pre-amplifier 336) through a resistance 318 and condenser 319, or through a resistance 320 and condenser 322 in series, or through a condenser 324, depending upon the position of a rotary switch 326 which is so constructed that only one of these three circuits is closed at one time. The condenser 319 is of relatively small value and is effective to suppress key click transients without materially affecting the tone quality. The condenser 322, on the other hand, is of sufficient value to bring about desirable changes in tone quality. The terminal 314 may also be connected to the point 312 through a condenser 328 which may be connected to a terminal 330, or through a conductor 332, the terminal 314 being more or less permanently connected to the terminal 330 through a resistance 334. For the sake of simplicity the switches for these circuits are indicated merely by arrow heads, but it will be understood that corresponding switches will be provided with gang operating means (such as the rotary switch device 326), so that they may be opened and closed simultaneously.

Terminal 316 is the point from which the common output signal for the whole instrument is derived and is thus shown as connected to a pre-amplifier 336, which in turn is connected to an amplifier 338, the latter supplying one or more speakers 340.

A resistance 342 is connected between the terminal 312 and a junction 344. A volume control means 346 is illustrated as connected between the terminals 316 and 344. This is a diagrammatic representation of a volume control device of the same kind as is used in electric organs and is described in my co-pending application Serial No. 91,284 filed July 18, 1936, and comprises a plurality of resistors 348 of different values which are adapted to be connected progressively in shunt with one another to change the resistance between the terminal 316 and junction 344. A swell pedal, or a suitable manual control (not shown), operates this switching and provides the player with an additional control of the output level, which is independent of his control through the touch responsive key action.

The circuits which may be selectively completed through the rotary switch 326 are series circuits, while the circuits from the terminal 314 which are completed through the condenser 328, conductor 332 and resistance 334 are in shunt. The impedances of the latter shunt circuits to various frequencies may be varied by means of the circuit elements shown as connected between the terminals 330 and 331, the terminal 331 being connected to the terminal 344. These elements comprise inductances 350 and 352 connected in series between the terminals 330 and 331. A pair of independently movable contact arms 354 and 356 are connected to a point 358 between the inductances 350 and 352. The switch arm 354 is adapted to make contact with one of the three terminals 360, 362 or 364, while the switch arm 356 is adapted to make contact with any one of the terminals 366, 368 and 370. Between the terminals 362 and 330 is located a condenser 372, and between the terminals 364 and 330 there is a condenser 374, the terminal 360 being directly connected to the terminal 330. Similarly, a condenser 376 is connected to the terminal 368 and the terminal 331, while a condenser 378 is connected to the terminal 370 and the terminal 331. The condensers 372, 374 and 378 are of different values, so that by connecting them in shunt with their associated reactances 350 and 352 in various combinations, a wide variety of different results may be obtained. Additional resonant circuits may be employed if it is desired to obtain a greater variety of tonal possibilities.

The wire 306, as well as corresponding wires for other groups of notes, may be connected to the terminals 316 and 344 in the same ways that the wire 308 may be connected to these terminals, as is clearly indicated in Figure 2.

The wire 310, representative of the wires leading from the control tubes of the lower notes of the scale, is connected to the terminal 316 in a manner substantially identical to the manner in which the wire 308 is connected to this terminal, but instead of using the same resonant mesh as is connected between the terminals 330 and 331, a similar resonant control device connected between terminals 380 and 381 is provided. The various elements of this impedance device have values differing from those of the corresponding elements in the variable shunt reactance device which is connected between the terminals 330 and 331. The terminal 381 of the shunt react-

ance device for the lower notes is connected to the terminal 344, which latter terminal is connected to ground through a condenser 382.

Changes in the values of the series and shunt impedances for each of the 22 circuits will, of course, change the relative intensities of the signals put out by each group of four notes. The nature of the impedances in the shunt and series paths changes the harmonic content produced in the output system by the different groups of notes. A series of gang switches makes it possible simultaneously to connect like impedances in each of the 22 circuits.

For example, the terminal 314 may be connected to terminal 316 through six different paths, three being shunt paths and three being series paths. One shunt path is through the resistance 334 and is permanently connected, while the others are capable of being closed at the election of the player.

In the arrangement which I consider preferable, the whole instrument is divided into two parts so that the shunt paths may be carried through the two separate groups of adjustable reactance meshes connected between the terminals 330-331 and 380-381. Assuming that the switch 354 is connected to the terminal 360 and the switch 356 is connected to the terminal 366, and that the series resistance 318 is used to connect the terminal 314 with the terminal 316, then the signal impressed upon the terminal 316 will be a faithful reproduction of the signals received from the control tubes connected to the wire 306. When the switch for resistance 318 is closed, the values of the resistances 318 and 334 will determine the amplitude of the signal output with respect to the signal received from other groups of four tubes. If now the resistance 318 be disconnected, and the series path through the condenser 324 be used, a change in tone quality will result because of the change of impedance offered by the series path with changes in frequency. Similarly, if the third series path between the terminals 314 and 316 be used, a different tonal result will be obtained, and likewise any of the numerous changes which may be made in the impedance of the shunt path will result in changes in tone, so that tones similar to those of the cello, violin and various other instruments may be obtained.

Modified note control switch mechanism

In Fig. 28 is shown a simplified form of key operated switching mechanism for controlling the intensity envelope of the note. In this figure, the control tube corresponds to the control tube 294 shown in Fig. 1, and the same reference characters have therefore been applied to this tube and such of the associated elements thereof as correspond to similar elements which have been previously described.

As in the previously described note intensity envelope controlling circuits, the cathode of control tube 294 is connected to ground through a condenser C₄ and has a terminal N which is connected to a terminal M through a high resistance R₇, the terminal M being connected to ground through a condenser C₇. In this construction, the key 420 presses an actuator 422 downwardly for the operation of two resilient switch fingers 424 and 426, which are mounted respectively below and above a rigid switch arm 428. The switch arm 428 is connected to the terminal M through a resistance R₈ while the switch finger 424 is connected to said terminal 75

- M through a resistance R_{18} . The switch arm 426 is connected to a junction 430 through a resistance R_{20} , and said junction 430 is connected to a terminal B_c of an adjustable direct current potential source through a resistance R_{21} , the junction 430 being connected to ground through a condenser 432. The switch finger 428 normally makes contact with a bus bar 434 which may be common to all of the key switches, or 5 may be made in sections, in the general manner exemplified in Fig. 30 with respect to the divided bus contact bar 244, one section for the treble register and the other section for the bass register. The bus bar 434 is connected to a terminal B_a of adjustable direct current potential. 10 If the bus bar is made in two or more sections for different registers of the instrument, means will be provided for separately adjusting the potential of each section.
- 15 The switch arm 424 normally makes contact with a bus bar 436 which is connected to a terminal B_b of adjustable direct current potential. A sustaining pedal 438 is diagrammatically illustrated as connected by a link 440 with a pivotally mounted shaft 442. The shaft 442 carries a strip 444 of insulating material which overlies the free 20 ends of all of the switch fingers 424 and is adapted, when the sustaining pedal 438 is depressed, to bend the switch fingers 424 to the 25 positions shown in dotted lines, thereby breaking the circuit between the switch fingers 424 and the terminal B_b . Upon the initial portion of the down stroke of the key, the switch finger 424 will be moved away from contact with the bus bar 436. 30 Thereafter the resilient switch finger 426 will be moved away from the bus bar 434, and subsequently brought into contact with the switch arm 428.
- 35 By means of this key operated switch mechanism, the potential upon the terminal M may be controlled in a variety of different ways to produce different note intensity envelopes. For example, if it is desired to obtain a note having a percussive attack, similar to that of the standard 40 piano (but not touch responsive), the potential of the terminal B_a is adjusted to be at a value in the order of -200 volts with respect to ground, and the potential of the terminal B_c adjusted to ground potential. Terminal B_b will of course be 45 set at safe cutoff potential. Under these circumstances, the condenser 432 will be charged to -200, volts so that upon depression of the key 420, the condenser 432 will be connected through resistor R_{20} , switch arms 426 and 428, and resistor 50 and R_{18} with the terminal M . Thus, the condenser C_7 will be rapidly charged, and the potential of the terminal M gradually lowered so that the plate current will rapidly increase, and the resultant note will have a percussive attack. Thus, 55 the note will not immediately sound at its maximum intensity, but will build up rapidly to its full intensity in a manner similar to that illustrated in Fig. 21. After the note has attained its maximum intensity, it will commence decaying gradually, due to the fact that condenser 432 is discharging through resistance R_{21} as well as 60 through the circuit which includes the terminal M . However, the note will not decay to zero intensity until the key is released, since the potential of the terminal M will be influenced by the 65 potential of terminal B_c , which terminal is connected through resistances R_{21} , R_{20} and switch arms 426, 428 and resistance R_{18} to the terminal M . During the interval that the key is held depressed, the switch arm 424 is held away from

contact with the bus bar 436, which is at cutoff potential. However, as soon as the key is released, switch arm 424 will flex upwardly and connect the terminal M to the cutoff potential source B_b through the resistor R_{18} . The resistor R_{18} will be of such value that the decay of the note to zero intensity will be rapid, but not too abrupt.

If it is desired to sustain the note after the key 420 has been released, the player will depress the 10 sustaining pedal 438 which will swing the insulating strip 444 clockwise and bend all of the flexible switch arms 424 downwardly (as shown in dotted lines, Fig. 28), so that all of the notes 15 which are sounding when the sustaining pedal is depressed, will decay logarithmically to a very low intensity level. Likewise, the depression of any key during the time that the sustaining pedal is depressed will result in the very gradual decay 20 of the note controlled by that key.

When it is desired to have the instrument play as an organ, the potential of the terminal B_a may be adjusted to a value such as -100 volts, and the terminal B_c adjusted to the same potential, while the potential B_b is maintained at a safe cutoff 25 potential. Under these circumstances, the notes will commence sounding with a gradual attack, due to the resistances R_{20} and R_{18} , and the condenser C_7 , but the potential of the condenser 432 will be maintained at the value of -100 volts 30 through the resistor R_{21} . As a result, the note having attained its maximum intensity as represented by the potential of, let us say -50 volts upon the terminal M , it will continue at this maximum intensity until the key is released, whereupon the note will decay rapidly because of the rapid decrease in the potential of the terminal M , due to the leakage of the charge of condenser C_7 35 through the resistor R_{18} , switch arm 424 and bus bar 436 to the cutoff potential source B_b , as 40 well as because of the discharge of the condenser C_7 through the plate circuit of the control tube. The intensity envelope will thus be similar to that shown in Fig. 26.

When it is desired to produce the effect of a 45 slow attack string instrument, the potential of the terminal B_a is adjusted to ground potential, the terminal B_c adjusted to a high value of negative potential such as -200 volts, and the terminal B_b is adjusted to safe cutoff potential. Under 50 these circumstances, the condenser 432 is initially discharged because the junction 430 is maintained substantially at ground potential through the resistance R_{20} , switch arm 426, bus bar 434, which latter is connected to the terminal B_a at ground potential. Upon depression of the key, this circuit connecting the junction 430 to ground is of course opened and the condensers 432 and C_7 are gradually charged through resistances R_{21} and R_{20} , switch arm 426, switch 55 arm 428 and resistor R_{18} . However, due to the fact that the resistance of R_{21} is high, the condensers 432 and C_7 will be charged very slowly, and the attack of the note will therefore be very slow. However, by holding the key depressed for 60 an appreciable length of time, the potential of the terminal M may be gradually lowered to the potential of -100 volts, and the intensity of a note thus raised to a high value. Thus, the player has at his command the ability to accentuate 65 certain notes of the score being played by holding certain keys depressed for longer periods than others. By this method, very entertaining and musically interesting slow attack stringlike effects may be obtained.

It will be readily apparent that by changing the potentials of the terminals 'Ba, Bb and Bc with respect to one another, the intensity envelopes of the notes sounded may be varied considerably to suit the requirements of the musical selection being rendered, and to suit the musical taste of the player or audience, as well as to pre-compensate for adverse acoustical conditions of the room in which the instrument is being played.

10 A comparison of the key circuit of Fig. 28 with that of Fig. 1 will disclose the fact that the former is substantially a simplified form of the latter, and that many of the functions of the key circuit of Fig. 1 are retained in the modified form of Fig. 28, and that the latter does not require the refined key action which is necessary in the former.

Many changes, substitutions, and modifications may be made in the instrument disclosed herein without departing from the more basic principles 20 of my invention. The accompanying claims are, therefore, intended to include within their scope such modifications, equivalents, and substitutions as will be readily suggested to those skilled in the art and whereby substantially the same results may be obtained in substantially the same way as disclosed herein.

In the following claims and in the foregoing specification, the potential of various points is described as of "ground" potential. This term 30 will be understood by those skilled in the art to mean any suitable fixed potential, whether adjustable or not, by which the desired effects may be obtained. Furthermore, in referring to a signal transmission circuit it is intended to include such parts of the output circuit, as for example the plate circuit of the control tube 294, through which the alternating component of the tone signal is transmitted, generally to the signal utilizing device, such as a loud speaker. Likewise, although reference characters are included in some of the claims, such reference characters are intended to facilitate an understanding of the meaning of the claims, and are 40 not intended as specifically limiting the claims to the specified part of the exemplary embodiment of the invention which is shown in the drawings.

In the foregoing specification various constants for the electrical elements have been set forth. These constants are merely illustrative and, as will be readily apparent to those skilled in the art, may be varied considerably, especially if compensatory changes are made in values of 50 other elements of the circuits, and I therefore do not wish to be limited to the values given or to the other precise details of the invention set forth herein, except as required by the claims which follow.

60 I claim:

1. In an electrical musical instrument playable by keys and having for each key thereof a terminal the potential of which determines the intensity of the note produced upon operating said key, means to control the potential on said terminal comprising a bucket condenser, a tank condenser, a source of potential, switch contacts normally connecting said source to said bucket condenser, a second set of switch contacts for connecting said bucket condenser to said terminal, means operated by said key successively to open said first switch contacts and close said second switch contacts, and means to dissipate a portion of the charge of said bucket condenser 60 during the interval between the opening of said

first contacts and closure of said second contacts, said last named means comprising, a second potential source having means for adjusting its value, a resistance element connected thereto, and switch means for connecting said second potential source through said resistance element to said bucket condenser for a period determined by the velocity of key operation. 5

2. In an electrical musical instrument playable by keys and having for each key thereof a terminal the potential of which determines the intensity of the note produced upon operating said key, means to control the potential on said terminal comprising a condenser, a source of potential, switch contacts normally connecting 10 said source to said condenser, a second set of switch contacts for connecting said condenser to said terminal, means operated by said key successively to open said first switch contacts and close said second switch contacts, and means to 15 dissipate a portion of the charge of said condenser during the interval between the opening of said first contacts and closure of said second contacts, said last named means comprising, a second potential source of adjustable value, a resistance element, and switch means for connecting 20 said second source, said resistance element, and said condenser in series for a short period determined by the velocity of key operation. 25

3. In an electrical musical instrument, the combination of a source of electrical impulses of musical frequency, an output circuit, a multi-electrode thermionic tube receiving impulses from said source and having an electrode the potential of which determines the amplitude of the signal 30 which is transmitted to said output circuit, a normally charged condenser, a resistor having one terminal connected to said electrode, a second condenser connected to the other terminal of said resistor, a key operated switch normally 35 connecting said normally charged condenser to a potential source, a second resistor connected to said normally charged condenser for slowly discharging the same, and means for connecting said normally charged condenser to said second condenser upon actuation of said key operated switch, whereby said condensers are connected in parallel and will therefore equalize their 40 charges and discharge gradually through both of said resistors. 50

4. In an electrical musical instrument, the combination of a source of electrical impulses of musical frequency, an output circuit, a multi-electrode thermionic tube receiving impulses from said source and having an electrode the potential 55 of which determines the amplitude of the signal which is transmitted to said output circuit, a normally charged condenser, a resistance element having one terminal connected to said electrode, a second condenser connected to the other terminal of said resistance element, and a key controlled switch normally connecting said normally charged condenser to an adjustable potential source thereby to maintain said condenser charged, said key switch being operable upon depression of the key sequentially to disconnect said normally charged condenser from said charging source and to connect it to said second condenser and to said other terminal of said resistance element. 60

5. In an electrical musical instrument playable by keys and having for each key thereof a terminal the potential of which determines the intensity of the note produced upon operating said key, means to control the potential on said ter- 70

- 5   minal comprising, a tank condenser connected to said terminal, a bucket condenser, a source of potential, switch contacts normally connecting said source to said bucket condenser, a second set of switch contacts for connecting said bucket condenser to said tank condenser, means operated by said key upon its operating stroke successively to open said first switch contacts and close said second switch contacts, leakage means 10 to dissipate a portion of the charge of said bucket condenser during the interval between the opening of said first contacts and closure of said second contacts, a relatively low resistance circuit for discharging said tank condenser, a sustaining switch opened upon operation of said key and included in said circuit, and sustaining means operable at will to hold said sustaining switch open after the operated key has been released.
- 15   6. In an electrical musical instrument playable by keys and having for each key thereof a terminal the potential of which determines the intensity of the note produced upon operating said key, means to control the potential on said terminal comprising; a first condenser connected to said terminal; a second, normally charged, condenser; a switch operated by said key to connect said second condenser to said first condenser; means responsive to the velocity of the 20 operation of said key to dissipate a portion of the charge on said second condenser; and means operable just prior to the closure of said switch for dissipating any undesired residual charge which may be present on said first condenser.
- 25   7. In an electrical musical instrument in which the note sounded is controlled by a first circuit including a condenser normally charged insufficiently to cause the note to sound, a key, a second circuit, switch means in said second circuit and operated by said key for supplying electrical energy to said first circuit, a third circuit, and a repeat switch in said third circuit and operated by said key during the down-stroke thereof to connect said condenser to a potential source of 30 value such as will assure a normal charge on said condenser prior to the completion of the down-stroke of said key.
- 35   8. In an electrical musical instrument playable by keys and having for each key thereof a terminal the potential of which determines the intensity of the note produced upon operating said key, a source of predetermined potential, and a switch interposed between said terminal and said source for connecting said terminal to said source for a brief interval during the operative stroke of 40 said key.
- 45   9. In an electrical musical instrument playable by keys and having for each key thereof a terminal the potential of which determines the intensity of the note produced upon operating said key, means to control the potential on said terminal comprising a switch operated by said key to connect said terminal to a source of electrical energy, a pair of relatively movable contacts, one 50 of said contacts being connected to said terminal, and the other of said contacts being connected to a supply of predetermined potential, and means operated by said key to close and open said contacts in quick succession prior to the 55 closure of said switch.
- 60   10. In an electrical musical instrument playable by keys and having for each key thereof a terminal the potential of which determines the intensity of the note produced upon operating said key, means to control the potential on said 65
- 65   terminal comprising a switch operated by said key to connect said terminal to a source of electrical energy, a supply of potential of adjustable value, and means operated by said key temporarily to connect said supply to said terminal incidental to the operating stroke of said key. 70
- 70   11. In an electrical musical instrument playable by keys and having for each key thereof a terminal the potential of which determines the intensity of the note produced upon operating said key, means to control the potential on said terminal comprising a switch operated by said key to connect said terminal to a supply of electrical energy, a source of potential, and repeat contacts closed and opened by said key just prior to the closure of said switch and operable to connect said terminal to said potential source. 75
- 75   12. In an electrical musical instrument playable by keys and having for each key thereof a terminal the potential of which determines the intensity of the note produced upon operating said key, means to control the potential on said terminal comprising a switch operated by said key to connect said terminal to a source of electrical energy, and means having operative connection with said key and operable thereby just prior to the operation of said switch temporarily to connect said terminal to a source of predetermined potential. 80
- 80   13. In an electrical musical instrument playable by keys and having for each key thereof a terminal the potential of which determines the intensity of the note produced upon operating the key, means to supply a predetermined potential determining the maximum potential attainable by said terminal upon operation of said key, thereby to determine the maximum intensity of the note sounded, a sustaining pedal, adjustable means to determine the intensity of the note sounded after release of the key and during the time that the sustaining pedal is depressed, and means to control the rate of decay of the note. 85
- 85   14. In an electrical musical instrument, the combination of a plurality of electrical generators of tone frequency impulses, means for translating into sound the electrical impulses produced by said generators, and key operated means for controlling the amplitude of the sound produced by said translating means including adjustable means for controlling the rate of attack, adjustable means for controlling the rate of decay, and adjustable means for controlling the amplitude of the sound upon release of the key. 90
- 90   15. In an electrical musical instrument playable by keys and having for each key thereof a terminal M, the direct current potential of which determines the intensity of the note produced upon operation of the key, a plurality of terminals Ba, Bb, Bc connectible to sources of direct current potential, a condenser, key operated switch means normally connecting said terminal Ba to said condenser and operable upon depression of said key to connect said condenser to said terminal M and to disconnect said terminal M from said terminal Bb, and a resistor connecting said condenser to said terminal Bc. 95
- 95   16. In an electrical musical instrument playable by keys and having for each key thereof a single terminal M, the direct current potential of which determines the intensity of the note produced upon operation of the key, a multiple switch, a condenser, a plurality of terminals Ba, Bb, Bc of direct current potential, a high resistance element connected between said terminal Bc and said condenser, a resistor connected 100

between said condenser and said terminal B_a through normally closed contacts of said switch, a second resistor connecting said terminal M with said terminal B_b through a second pair of 5 normally closed contacts of said switch, and means operable upon depression of said key to separate said pairs of switch contacts, and to connect said first resistor to said terminal M.

17. In an electrical musical instrument playable by keys and having for each key thereof a single terminal, the direct current potential of which determines the intensity of the note produced upon operation of the key, a pair of resistors connected to said terminal, a potential source of value which when impressed upon said terminal is insufficient to cause the sounding of the note, said source being normally connected to said terminal through one of said resistors, a condenser normally charged to a potential sufficient when impressed upon said terminal to cause sounding of a note, and switch means operated by said key to connect said condenser to said terminal through the other of said resistance elements.

18. In an electrical musical instrument having a keyboard, a plurality of playing keys, each playing key operating a plurality of contacts operable in timed succession, the timed intervals of which are dependent upon the velocity with which the key is operated, each said key being associated with a continuously operating vacuum tube producing a signal having a fundamental pitch associated with a note of the scale, a second control tube connected to receive a signal from said first tube, connections from said key switches to control the operation of said control tube to make said control tube operative to transmit and modify the signal from said first tube, an output circuit which is common for a plurality of said control tubes, and means to translate said common output signal into sound.

19. In an electrical musical instrument having a keyboard, a key, a switching device operated by said key, a signal transmission circuit associated with said key more particularly than with other keys of said keyboard, a terminal having a direct current potential with respect to a reference point of fixed potential, said terminal potential determining the amplitude of the output signal in said transmission circuit, a condenser connected between said terminal and some point of fixed potential, a first circuit controlled by said switching device to furnish current to alter the charge on said condenser in one direction at a rapid rate but for a limited period of time, a second circuit controlled by said switching device to furnish current to alter the charge on said condenser in the same direction at a lesser rate but for an unlimited period of time, and a third circuit for altering the charge on said condenser in the opposite direction at a decreasing rate until the amplitude of said output signal becomes substantially zero.

20. The combination set forth in claim 19, and including a fourth circuit for altering the charge on said condenser in a direction opposite to that of said second circuit.

21. The combination set forth in claim 19, and including a sustaining pedal, and a fourth circuit controlled by said sustaining pedal for altering the charge on said condenser in a direction opposite to that of said second circuit.

22. The combination set forth in claim 19, and including a sustaining pedal, a switch operated in part by said key and in part by said sus-

taining pedal, and a fourth circuit controlled by said switch for altering the charge on said condenser in a direction opposite to that of said second circuit.

23. The combination set forth in claim 19, and including a sustaining pedal, a switch operated by said key, means operated by said sustaining pedal to maintain said switch in operated condition, and a fourth circuit including said switch for altering the charge on said condenser in a direction opposite to that of said second circuit.

24. The combination set forth in claim 19, in which said first circuit includes a second condenser.

25. The combination set forth in claim 19, in which said first circuit includes a second condenser, and an adjustable potential source is provided to maintain a preselected charge on said condenser while said key is in normal position.

26. The combination set forth in claim 19, in which said first circuit includes a second condenser, and in which said switching device includes means for altering the charge on said second condenser during a portion of the operative stroke of said key.

27. The combination set forth in claim 19, in which said first circuit includes a second condenser, and which includes a terminal B of adjustable potential, a resistor having one end connected to said terminal B, and in which said switching device includes means for connecting said second condenser to the other end of said resistor during a portion only of the operative stroke of said key.

28. The combination set forth in claim 19, in which said first circuit includes a second condenser, and said switching device includes means for altering the charge on said second condenser to an extent determined by the velocity of key operation.

29. The combination set forth in claim 19, in which said first circuit is provided with key velocity controlled means for determining the rate at which said first circuit will alter the charge on said condenser.

30. The combination set forth in claim 19, in which said third circuit includes a current limiting resistor connected between said terminal and said transmission circuit.

31. The combination set forth in claim 19, in which said third circuit comprises a resistor connected between said terminal and a point of adjustable direct current potential.

32. The combination set forth in claim 19, including a source of adjustable direct current potential connected in one of said circuits, whereby the player may alter the note intensity envelope by adjusting said potential.

33. The combination set forth in claim 19, and including an electron discharge device having a cathode and an anode; and a high resistance; in which said third circuit is completed from said terminal through said high resistance and the cathode-anode circuit of said electron discharge device.

34. In combination, an electrical source of a musical signal including a generator and output circuit therefor, said source supplying a signal of a wave form having substantially rounded peaks, a multi-electrode thermionic discharge device having a cathode, grid, and plate; a connection from said source to impress a signal on said grid in which said peaks are the peaks of most positive potential, a resistor in the circuit of said cathode connected so that the direct current

voltage drop across said resistor due to cathode current appears as a biasing voltage between said cathode and said grid to bias said grid more negatively with respect to said cathode with increasing direct current in said resistor, a source of direct current, and a circuit carrying current from said direct current source through said resistor into said cathode, the amplitude of said signal, the characteristics of said tube, and the 5 value of said resistor being so chosen that great distortion of said signal takes place, and that the output signal of said discharge device contains a fundamental frequency and a series of musically desirable harmonic frequencies in which the 10 energy of the harmonics, relative to the energy of the fundamental, increases with increasing current into said cathode.

35. In a musical instrument, the combination set forth in claim 34, in which said discharge 20 device has a screen between said grid and plate, and a connection for maintaining said screen at a fixed potential with respect to ground, whereby said output signal will be blocked when said cathode current decreases to zero.

36. In an electrical musical instrument, the combination set forth in claim 34, and a velocity responsive key circuit, connected to supply increasing amounts of cathode current to said discharge device when said key is operated with increasing velocity, whereby the output signal of 30 said discharge device will contain increasing proportions of harmonic energy with increasing velocity of key operation.

37. In a musical instrument the combination 35 set forth in claim 34, in which said direct current source consists of a condenser, and a key-operated switch for connecting said condenser to supply cathode current to said discharge device for a limited period of time and at a decreasing 40 rate, whereby said output signal will have greater relative harmonic energy, when the current is being supplied at a rapid rate, and will then have decreasing relative harmonic energy as said rate decreases.

38. In a musical instrument having a plurality 45 of keys forming a keyboard, the combination as set forth in claim 34 for each of said keys, in which the constants of the various circuits are chosen so that the amplitude and wave form of 50 the signal supplied to said discharge devices for the higher notes cause the latter to produce output signals of lesser harmonic energy than do the devices for the lower notes.

39. The combination set forth in claim 34, in 55 which said source of direct current is a condenser.

40. In an electrical musical instrument, the combination of an electron discharge device having a cathode, grid, screen, and plate, a generator connected to supply a signal between said grid 60 and ground, said grid having a connection affording a direct current path to ground, a source of direct current potential more negative than ground and having a terminal C, a terminal M, a resistor connecting said terminal M to said cathode, condensers respectively connecting said terminal M and said cathode to ground, a key-operated switch for connecting said terminal C to said terminal M, a source of direct current potential 65 more positive than ground and having a terminal 70 344, an impedance connecting said terminal 344 to said plate, and a connection for maintaining said screen at a fixed potential relative to ground.

41. The combination set forth in claim 19, in which means controlled by said key are provided 75 rapidly to bring said terminal to a predetermined

fixed potential for a short interval during the operative stroke of said key.

42. The combination set forth in claim 19, and including a switch closed by said key for a brief interval during the operative stroke thereof, a 5 source of direct current potential, and a low impedance circuit controlled by said switch for bringing the potential of said terminal to that of said source.

43. In an electrical musical instrument play- 10 able by keys and having for each key thereof a terminal the potential of which determines the intensity of the note produced upon operating said key, means to control the potential on said terminal comprising a condenser, a switch in- 15 cluding a pair of contacts one connected to said terminal, said switch being operated by said key to connect said condenser to said terminal at the completion of the downstroke of said key, means controlled by said key and responsive to the 20 velocity of operation thereof to change the charge on said condenser prior to its connection to said terminal, and means for changing the rate at which said velocity responsive means is capable of changing the charge on said condenser. 25

44. In an electrical musical instrument play- 30 able by keys and having for each key thereof a terminal the potential of which determines the intensity of the note produced upon operating said key, means to control the potential on said terminal comprising a condenser, a source of 35 electrical potential, switch contacts normally connecting said source to said condenser, a second set of switch contacts connected to said condenser and to said terminal respectively, means operated by said key successively to open said first switch contacts and close said second switch contacts, means to dissipate a portion of the 40 charge of said condenser during the interval between the opening of said first contacts and closure of said second contacts, and a high resistance element having one end permanently connected to said condenser and its other end connected to a source of adjustable potential. 45

45. In an electrical musical instrument capable 45 of simulating the musical performance of a piano, a key, an electrical switch connected for operation by said key, a sustaining pedal, and means coacting with said switch and operated by said pedal for preventing the operation of said switch 50 during the up-stroke of said key but permitting normal operation of said switch during the down-stroke of said key.

46. In an electrical musical instrument capable 55 of simulating the musical performance of a piano, a key, an electrical switch operated by said key, a sustaining pedal, means coacting with said switch and operated by said pedal for mechanically preventing the operation of said switch 60 during the up-stroke of said key. 65

47. In an electrical musical instrument play- 65 able by keys and having for each key thereof a terminal the potential of which determines the intensity of the note produced upon operating said key, means to control the potential on said terminal comprising a bucket condenser, a tank 70 condenser connected to said terminal, a resistance element having one end thereof connected to said tank condenser and to said terminal, and a switch having an operative connection with said key and operated thereby to connect said bucket condenser to said tank condenser and to said resistance element. 75

48. In an electrical musical instrument, a cir- 75 circuit having key operated means for sounding a

note and means for sustaining the note after the key is released, means to normalize said circuit to cause discontinuance of the sounding of the note, and means operated by said key just prior to the completion of the down-stroke thereof to cause operation of said normalizing means.

49. In an electrical musical instrument, the combination of a generator of electrical impulses containing a fundamental and successive harmonics progressively decreasing in amplitude in a geometric ratio, means for translating said im-

pulses into sound, a manually operable key for controlling the transmission of said impulses to said translating means, and means including a resistance and capacity network, a control tube and a switching device operated incidental to the operation of said key, said means being effective to change the quality of the tone produced upon operation of the key by changing the geometric ratio of the amplitudes of the harmonics.

August 9, 1938.

LAURENS HAMMOND.

It is hereby certified that error appears in the printed specification of the above numbered patent requiring correction as follows: Page 8, second column, line 33, for the word "from" read form; line 70, for "shuts" read shunts; page 9, second column, line 12, for "or" read of; page 20, first column, line 3, claim 34, for "asid" read said; and that the said Letters Patent should be read with this correction therein that the same may conform to the record of the case in the Patent Office.

Signed and sealed this 18th day of October, A. D. 1938.

Henry Van Arsdale

(Seal)

Acting Commissioner of Patents.

DISCLAIMER

2,126,464.—*Laurens Hammond*, Chicago, Ill. ELECTRICAL MUSICAL INSTRUMENT. Patent dated August 9, 1938. Disclaimer filed July 15, 1939, by the patentee.

Hereby enters this disclaimer to the combination covered by claim 46 of said patent except when the switch set forth in said claim controls a signal from a source which supplies the signal continuously, irrespective of the positions of said key and said sustaining pedal.
